UNITED STATES PATENT OFFICE.

LOUIS F. DIETER, OF BUFFALO, NEW YORK.

ROLLED METAL CAR-WHEEL OR SIMILAR BODY.

1,246,067.

Specification of Letters Patent. Patented Nov. 13, 1917.

Original application filed June 15, 1911, Serial No. 633,343. Divided and this application filed January 10, 1917. Serial No. 141,558.

To all whom it may concern:

- Be it known that I, LOUIS F. DIETER, a citizen of the United States, residing at Buffalo, in the county of Erie and State of New York, have invented new and useful Improvements in Rolled Metal Car-Wheels or Similar Bodies, of which the following is a specification, accompanied by seven sheets of drawings.
- 10 The features of my invention claimed herein have reference to the invention of my original application filed June 15, 1911, Serial No. 633,343. This application is a division of said original application and, 15 the parts of an apparatus or mill such as I prefer to employ to carry out my invention and shown in the accompanying drawings are illustrative of parts of my said original application.
- 20 The method of and means I prefer to employ for producing car wheels or other circular articles embodying my invention form no part of this invention, as this is claimed in and the present invention is also described or partly described in the following applications filed by me, viz: said original application for patent filed June 15, 1911, Serial No. 633,343; application for patent filed October 10, 1916, Serial No. 124,921; 25 application for patent filed November 20, 1916, Serial No. 132,372; application for patent filed November 22, 1916, Serial No. 132,815; and application for patent filed June 22, 1917, Serial No. 176,333.
- 30 The invention relates to car wheels or other circular articles formed integral or in one piece and having a central or hub and web portion, and a rim or marginal portion.
- 35 One object of my invention is to provide such articles wherein, during the rolling or forming of the marginal or rim portion thereof, the metal has been compressed to greater density than the metal in the central or hub and web portion.
- 40 Another object is to provide such articles wherein, during the rolling or forming process, the metal in the marginal or rim portion, except the metal forming the periphery or flanged tread portion, has been compressed to greater density or refinement than the metal in the central or hub and web portion, and the metal forming the periphery or flanged tread portion has been 45 compressed to still greater density or refine-
- ment than the metal in the remainder of said marginal or rim portion.
- 50 Another object is to provide such articles wherein the periphery or flanged tread portion is formed of metal of harder and of greater strength than the body portion.
- 55 Another object of my invention is the provision of such articles wherein the marginal or rim portion is formed stronger, more true and more durable than have been heretofore produced.
- 60 Another object is to provide such articles which are completely rolled or formed and wherein the metal in the marginal or rim portion is compressed to uniform and to its maximum density or refinement, or approximately so.
- 65 Another object is to provide such articles in either dished or undished form and composed of the same quality or qualities of metal as specified in the foregoing objects of my invention.
- 70 Another object is the provision of a dished wheel which is free or substantially free from initial or inherent stresses or strains.
- 75 Another object is to provide such articles as above specified each formed in one heat with all its surface smooth and all its angles sharp and free from fins or other undesirable projecting parts.
- 80 Another object is to provide such articles as above specified each formed at one or both sides with a preliminary central hole or a part or parts thereof, all in one heat in the same apparatus or mill.
- 85 Another object is to provide such articles which are true to their axes and which when on their axles or shafts are truly balanced or approximately so.
- 90 Another object is to provide such articles which when completely rolled have their central portions or hubs and web portions, and their marginal or rim portions formed smooth without leaving any raised portions or fins which would have to be removed afterward by turning or other costly means.
- 95 A further object is the provision of a wheel rolled from an ingot, bloom, blank or other work-piece and having a punched or pierced hub, a web and a rim, all surfaces and angles of which are smooth and free from surplus metal which would have to be removed afterward by turning or other costly means.
- 100 A further object is to provide a car wheel

110

rolled with one heat without surplus metal which would have to be removed afterward by turning or other costly means.

A further object is to provide a car wheel 5 wherein also the hub portion is rolled smooth and to proper form.

Still further objects are to provide a rudimentarily formed car wheel rolled on its periphery with two cylindrical or approximately cylindrical portions, one of which 10 is of greater diameter than the other, and an intermediate concaved or conical portion merging into said cylindrical portions, or approximately so; to provide a rudimentarily formed car wheel whose inner peripheral face or faces are rolled sufficiently inclined outwardly toward the periphery of the wheel to have condensed or compressed the metal therein to uniform or to practically uniform density, and to provide a car wheel otherwise improved over wheels as now made.

The invention consists in novel car wheels or other circular articles of manufacture 25 formed integral or in one piece and having a central portion or hub and web portion, and a rim or marginal portion herein described and more particularly pointed out in the claims, said central or hub and web portion being also termed the "body-portion" of the wheel or other article.

I prefer to carry out my invention with an apparatus or mill of the kind described and claimed in my aforesaid original application and in applications filed by me and having the hereinbefore mentioned serial numbers and filing dates.

In the accompanying drawings, in which I illustrate my invention together with devices or means I prefer to employ in carrying out my invention:

Figure 1 is a plan view, illustrating in a diagrammatic manner part of one form of a novel apparatus or mill, hereinafter described and also fully described in my aforesaid original application and, which I prefer to employ in the manufacture of my invention. The piercers or work-supporting means in this figure show a work-piece centrally and axially supported thereby with pressure applied equally to said work-supporting means at opposite sides of the work-piece, the work-piece being pierced or centered thereby and is shown rolled with one 55 set of rolls.

Fig. 2 is a similar view showing greater pressure applied to said work-supporting means at one side of the work-piece than at the other, thereby dishing the work-piece. 60 The work-piece in this figure is shown completely rolled with all the rolls and dished to the form shown.

Fig. 3 is a similar view illustrating said work-supporting means and the rolls moved 65 away from the work-piece and the work-

piece or finished article ready to be removed from the apparatus or mill.

Figs. 4 to 11 inclusive, illustrate the rolling or forming of the circular forms or shapes, for instance, from ingots, blooms, 70 blanks or other work-pieces into car wheels or other circular articles and, also illustrate rerolled, reformed or reworked car wheels. In each of these figures, the sections shown are half or diametral sections. For instance, in Fig. 4 the ingot, car wheel blank or other work-piece is shown rolled to the undished form of the wheel with the inner circumferential faces of the rim portion rolled to rudimentary form or sufficiently inclined, as and for the purpose hereinafter described with reference to Figs. 15, 33 and 34; the peripheral face or tread and flange portion of the rim being rolled to beaked or rudimentary form. In Fig. 5 said undished 80 wheel is shown rolled and dished to finish. Said Figs. 4 and 5 clearly illustrate the process of rolling the object, first into rudimentary undished form and then into finished dished form, all of which I prefer to do with one heat and in the same apparatus or mill. In Fig. 6 is illustrated the process for reworking or rerolling a car wheel. In Fig. 7 is shown a finished undished car wheel. In Fig. 8 the ingot, bloom, blank or 90 other work-piece is shown rolled to the undished form of a wheel having the web connecting its hub and rim portions formed at one side of the wheel with the inner circumferential face of the rim portion rolled to rudimentary form and sufficiently inclined as and for the purpose hereinafter described with reference to Figs. 16 and 33, the peripheral or tread and flange portion of the rim being rolled to beaked or rudimentary form. In Fig. 9 the undished wheel illustrated in Fig. 8 is shown rolled and dished to finished form. In Fig. 10 is shown for instance, a finished dished disk-wheel or a dished center such as used for tired car wheels, rolled and dished according to my method. In this figure, the rolls and piercers or work-supporting means are in the position or substantially in the position they occupy at the end of the rolling and dishing process. In Fig. 11 is shown, for instance, certain steps for forming lateral extensions or hub portion onto a work-piece and for confining or limiting the lateral and radial flow of metal at the central or hub portion during the process of forming said lateral extensions or hub portion.

Fig. 12 shows, for instance, a blank (of which is shown the center portion only), in position ready to be pierced or centered with said piercers or centers, or supporting means shown in solid lines; and it also shows, in dotted lines, said blank pierced or centered by said piercers or supporting means.

Figs. 13 and 14 illustrate more fully steps for forming the central or hub portion of my improved car wheel or other circular article smooth on all its surfaces and to the 5 desired form or shape without leaving a raised circular portion or fin which would have to be removed afterward by turning or other costly means.

Figs. 15 and 16 illustrate the flow of metal, 10 for instance, in the outer or rim portion of a work-piece during the process of rolling my improved car wheel or other article (see also Figs. 33 and 34).

Fig. 17 shows a blank or work-piece 15 which, according to certain steps employed in the manufacture of my invention, is shown pierced and centered in the apparatus or mill with said piercers or work-supporting means having for instance the 20 form as shown; said blank or work-piece being held rotatably in position ready to be rolled. In this figure the hub portion is shown in dotted lines rolled onto the work-piece by the rolls shown in dotted lines, 25 which also illustrate my method for forming lateral extensions or a hub portion onto a work-piece and for confining the lateral and radial flow of metal in the hub portion during the process of rolling or forming said 30 lateral extensions or hub portion. In this figure are also shown the rolls in the positions they will occupy, either during the time the ingot, bloom, blank or other work-piece is put into the apparatus or mill, or 35 when the work-piece or the finished wheel or other finished article is removed from the apparatus or mill.

Figs. 18, 19 and 20 show the flange and tread portion of car wheels and are diagrammatic views illustrating for instance a 40 few shapes or ways of "beaking", as herein-after described and also described in my said original application.

Figs. 21 to 25 inclusive illustrate certain 45 rolling or forming steps in rolling or forming the finished dished car wheel embodying my invention; for instance, a wheel such as shown in Fig. 5. In said Figs. 21 to 25 are illustrated certain steps for piercing and 50 rolling or forming a heated car wheel blank or work-piece, such as shown for instance in the Fig. 21 or Fig. 22, into the form of the finished dished car wheel shown in the Figs. 26 and 27.

55 Fig. 28 shows, for instance, the center portion of a blank or work-piece provided with a cylindrical hole, and in Fig. 29 is shown said blank or work-piece centered or pierced or penetrated and centered.

60 Figs. 30 and 31 illustrate diagrammatically improper flow of metal resulting from 65 improper working of the metal in the rim portion of a car wheel or other object having a web formed integral with the rim portion, during the forming of said rim portion, all

of which is avoided in the manufacture of my invention, as hereinafter described and also described in my said original application.

Fig. 32 illustrates, for instance, the proper 70 flow of metal during the forming of a tire having no web, such as used for some tired car wheels.

Figs. 33 and 34 are diagrammatical illustrations showing more fully the result of 75 rolling or forming the rim of a car wheel embodying my invention, as illustrated for instance on a small scale in the Figs. 4, 5 and 15; all as hereinafter described and also as described in my said original application. 80 Fig. 35 is an enlarged sectional elevation of a dished car wheel embodying my invention, the same being shown with its hub bored. Fig. 36 is an enlarged sectional elevation of an undished car wheel embodying my invention, the same being shown with its hub 85 bored.

Figs. 37 to 40 inclusive illustrate, for instance, such rolling or forming process or steps wherein the entire opposite end faces 90 of the hub of a work-piece are rolled or formed or operated upon directly with the herein named edging and web rolling rolls, during the process of rolling or forming said hub. It is, of course, understood that I 95 do not intend to limit myself to the use of the particular parts shown nor to the use of the apparatus or mill shown and described in my said original application, as other means may hereafter be devised for carrying 100 out my invention in a practicable manner.

Similar characters of reference indicate corresponding parts throughout the several views.

E, E are the spindles or axles named herein the work-supporting axles which also serve other purposes. At one end of said axles are removably fastened thereto piercers or work-supporting centers or work-supporting means, for instance E¹, E¹ or E², E² 105 or E^a, E^a, &c. These piercers, or centers, or supporting means may also be differently formed than those herein shown and may also serve other purposes, such for instance as forming dies, &c. There is practically no 110 limit to the forms or shapes that said piercers, or centers, or supporting means may have.

F, F¹ and F² represent the work-piece from some of the various forms or shapes it 115 may have when put into the apparatus or mill to some of the many various forms or shapes which the finished article or product may have (see also my said original application).

G, G are the roll shafts which have at one of their ends the herein named web finishing rolls.

G^a, G^a and G¹, G² and G³, G⁴ for instance, are sets of different shapes of the said herein 130

named web finishing rolls. These rolls are laterally movable and are also axially adjustable or movable and interchangeable. There is practically no limit to the forms or shapes that these rolls may have. These rolls, for instance, G¹, G² are connected together by equalizing mechanism, in such manner that said rolls may be connected with or disconnected from said equalizing mechanism, without disconnecting said rolls from the coöperating pressure cylinders or pressure devices operatively connected with said rolls, as described in my said original application; or they may be otherwise arranged if desired.

H is the herein named tread or face finishing roll which acts against the peripheral face of the work-piece. This roll is movable toward and against and also away from the peripheral face of the work-piece. The peripheral or rolling face of this roll may have many different shapes, as for instance H¹ in Figs. 1, 4 to 9, 17 and 21; or for instance as H² in Fig. 10; or for instance, as described in my said original application. There is practically no limit to the forms or shapes the peripheral or rolling face of this tread or face finishing roll may have.

J, J are the roll shafts, each of which has at one of its ends one of the herein named edging and web rolling rolls. Said rolls are either removably attached to said shafts in such a way that the whole roll may be driven by the shaft, or only part of the roll may be driven by the shaft and the other part be permitted to turn loose; or the whole roll may be permitted to turn loose on a journal removably fastened to the shaft, as fully described in my said original application.

J⁰, J⁰ and J¹, J² and J³, J⁴ and J⁵, J⁶ for instance, are sets of the herein named edging and web rolling rolls, shown in different shapes. These rolls are laterally and also axially movable and are interchangeable. There is practically no limit to the forms or shapes these rolls may have. These rolls, for instance J¹, J² are connected together by equalizing mechanism, in such manner that said rolls may be connected with or disconnected from said equalizing mechanism without disconnecting said rolls from the coöperating pressure cylinders or pressure devices operatively connected with said rolls, as described in my said original application, or they may be otherwise arranged if desired.

K is the herein named tread or face rolling roll which acts against the peripheral face of the work-piece to roll said face to a beaked or rudimentary form, or to partly finished form, or to finished form. This roll is movable toward and against and also away from the peripheral face of the work-piece and it is also laterally movable. The peripheral or rolling face of this roll may

also have various different shapes, as for instance K¹ in Fig. 1; or for instance as K² in Figs. 4, 5, 6, 7, 11 and 17; or for instance as K³ in Fig. 10; or, as for instance, a roll having its rolling face to suit the beaked form K⁶ of the peripheral face of a rim portion shown in Fig. 19; or, as for instance K⁷ in Figs. 8, 9, 21, 23, 24, 25 and 33, which is also the shape for rolling the peripheral face of a rim portion to the beaked or rudimentary form shown at K⁷ in Fig. 20; or for instance, as described in my said original application. Like the other rolls referred to, there is practically no limit to the forms or shapes that this roll may have.

Said face rolls H and K are connected together by equalizing mechanism, in such manner that said rolls may be connected with or disconnected from said equalizing mechanism without disconnecting said rolls from the coöperating pressure cylinders or pressure devices operatively connected with said rolls, as described in my said original application or they may be otherwise arranged if desired. Said face rolls H and K may also be moved toward and against or away from the peripheral face of the supported work-piece either together or independently of each other.

Said piercers or work-supporting means E¹, E¹ or E², E², &c., are located one at each side of the blank or other work-piece, and preferably revolve with the work-piece. For instance, during the piercing or penetrating or centering process, said piercers or work-supporting means are moved longitudinally toward or away from each other, or are moved as may be desired; and during the dishing process they are moved longitudinally with the central or hub portion of the work-piece, wheel or other article, as the case may be.

By the words "centering, or piercing or penetrating and centering" I mean that the ingot, bloom, blank or other work-piece is centered, or pierced or penetrated and centered in the apparatus or mill, by forcing either one or both said piercers or supporting means against or into said work-piece with the pressure cylinders O and N as for instance shown in Fig. 1 and, as and in the manner fully described in my aforesaid original application.

M, M are the herein named work-supporting heads, although so named they also serve other purposes, as will be observed from the matter hereinafter described and also from my said original application. The axles E, E are carried and rotatably supported by said supporting heads M, M. Each of said axles E, E has one of said herein named piercers or centers or supporting means for instance E¹ or E² or E⁶, &c., at one end. Said piercers or centers or supporting means are interchangeable. Said heads M, M are

longitudinally movable and are moved, with their axles E, E and said piercers or centers or supporting means for instance E¹, E¹ or E², E² or E³, E³; &c., in line with the axis of the work-piece by means of the pressure cylinders O and N (see Fig. 1), or by any other equivalent means. One of said heads M, M is operatively connected with the piston-rod O¹ of the piston in cylinder O and is moved by the pressure in said cylinder O, and, the other of said heads M, M is operatively connected with the piston-rod N¹ of the piston in cylinder N and is moved by the pressure in said cylinder N.

15 Figs. 1, 2 and 3 illustrate the preferred means for centering or for piercing or penetrating and centering ingots, blooms, blanks or other work-pieces, for supporting the same, for rolling, dishing or undishing, or 20 for rolling and dishing or undishing the same, and also for putting the work-pieces at their hub or center portions while so supported by said supporting means into clamped condition, laterally or axially be- 25 tween said piercers or supporting means and automatically keeping said hub or center portions in said clamped condition by constant pressure during the rolling and dishing or undishing process.

30 For piercing or centering, for instance, a properly heated blank or work-piece F, having the form shown in Figs. 12 or 22 (in Fig. 12, the center portion only is shown of said work-piece F), the blank or work-piece F which, in these illustrations, has a thickness which is for instance the same or some- 35 what greater than the lateral thickness or width which the marginal or rim portion of the car wheel or other article is to have 40 when finished, is placed on a positioning or raising, lowering and retaining mechanism (see my aforesaid original application) and therewith lowered to the position indicated in Fig. 12, wherein the outer por- 45 tion or periphery (not shown in Fig. 12) of said blank F will be central or co-axial, or approximately so, with said piercers or supporting means, for instance E¹, E¹, which latter will then be moved by the pressure 50 in said cylinders N and O acting on the pistons of the piston-rods N¹ and O¹ operatively connected with said piercers or work- supporting means, as shown for instance in Fig. 1, to the position shown for instance in Fig. 12. The total pressure or force will 55 then be delivered to the pistons of said piston-rods N¹ and O¹ to force, for instance, said piercers or supporting means E¹, E¹ or any other suitably formed piercers or 60 supporting means, as for instance E¹, E¹, &c., into said work-piece F to the depth or depths as indicated, for instance, by the dotted lines for said centers or supporting means E¹, E¹ in Fig. 12, or shown by the 65 solid lines, for instance, in Fig. 17. In case that the blank or work-piece has a thickness which is the same or somewhat greater than the length which the hub of the car wheel or other article is to have when finished, then in such case the shoulders or flanges e¹⁰, e¹⁰ of said piercers or supporting means E¹, E¹ will come against the sides of the blank or work-piece as for instance shown in the Figs. 1, 4, 14, 21 and 23. In Fig. 6 is shown, for instance, a previously finished or worn car wheel rerolled to the size and form of F¹, supported for instance by said piercers or centers or forming dies E², E², as shown. These piercers or centers or forming dies are forced or placed over the outer diameter of the hub as shown and serve either to reduce or enlarge the diameter of the bore of the wheel or other article, as may be desired. The piercing or center-portion of these centers or forming dies E², E² either centrally enters the hole loosely or will be centrally forced into the hole or bore of the work-piece, as shown in Fig. 6, and the annular flange which is separated from said piercing or center-portion by an annular intervening space, is centrally forced over or placed over the outer peripheral part or diameter of the hub of the work-piece, by which process the central hole or bore of, for instance, either 95 previously formed or worn car wheels, may either be reduced or made larger so that the same may be reboored to the diameter of its original bore or to a larger diameter. In Fig. 29 is shown a blank or work-piece 100 F which has previously been provided with a central hole as shown in Fig. 28, and which has been penetrated or centered with the piercers or supporting centers for instance E¹, E¹ as shown, the operating process being the same as before described and, said flanges or shoulders e¹⁰, e¹⁰ of said piercers or supporting means E¹, E¹ limit, in the operating process illustrated for instance in Fig. 17, the lateral flow of metal 110 during the process of forming the hub. The work-piece may also be centrally pierced or penetrated at only one side with one of said piercers or supporting means while the other side is only supported by the other piercer or supporting means, or, one side of the work-piece may be pierced or penetrated to a certain depth and the other side pierced or penetrated to a different depth, as and in the manner fully described in my aforesaid application. 115

120 For work-pieces to be pierced or penetrated at both sides, I prefer, in some cases, to make the length of said piercers or supporting centers to suit the location of the web portion, that is, the metal between the ends of said piercers or supporting centers, if any, or the ends of said piercers or centers, I prefer to be in a plane with that portion of the web which is adjacent the cen- 125 130

tral or hub portion, as for instance shown in Fig. 16.

With reference to Figs. 1, 2 and 3, the rolling or forming process may begin with the herein named edging and web rolling rolls, for instance J^1 , J^2 , and tread or face rolling roll K and therewith the blank or other work-piece may be rolled to either the forms or shapes F^1 , such as shown in Figs. 1, 4 and 24, or similar forms. In case the finished article should be a dished car wheel having the form or shape shown, for instance, in Figs. 3, 5, 25 or 26, the ingot, bloom, blank or other work-piece having been rolled by the herein named edging and web rolling rolls, for instance J^1 , J^2 and the tread or face rolling roll K , to the form or shape F^1 in Figs. 1, 4 or 24, and with said rolls in the position shown in Figs. 1, 4 or 24 or the rolls J^1 , J^2 may be moved somewhat toward the axis of the work-piece, the herein named web finishing rolls, for instance G^1 , G^2 and tread or face finishing roll H , may begin the finishing operation against the work-piece F^1 , and during said finishing operation the wheel may also be dished in the following manner:—

With the work-piece F^1 supported on said piercers or centers or supporting means, for instance, E^6 , E^6 and with its hub or center portion automatically firmly clamped laterally between said piercers or centers or supporting means and before the dishing commences, as shown in Fig. 1, the piston-rod N^3 of the cylinder N with one of said work-supporting heads M , M and its axle E and piercer or center E^6 now under constant and continuous pressure from said cylinder N , causes the one piercer or center E^6 to press automatically and continuously toward and against the hub or center portion of one side of said work-piece F^1 , and the piston-rod O^3 of the cylinder O with the other supporting head M and its axle E and piercer or center E^6 now also under constant and continuous pressure from the cylinder O , causes said other piercer or center E^6 to press automatically and continuously toward and against the hub or center portion of said work-piece F^1 at the other side thereof as shown in Fig. 1. Dishing of the work-piece then takes place, while the work-piece is rotating and while the marginal or peripheral portion of the work-piece is laterally supported and retained by the rolls as shown, in the following manner:—

While either, any, or all the driven rolls or all the rolls are in operation, the pressure in said cylinder N is gradually somewhat relieved or reduced, retaining therein however the constant pressure required in said cylinder N to retain the aforesaid automatically clamped condition of the hub or center portion of said work-piece later-

ally between said piercers or centers E^6 , E^6 , thereby causing the pressure or force in the cylinder O to overcome the resistance of the piston-rod N^3 and gradually moving the pistons and the rods O^2 , N^2 and O^3 , N^3 , with their said heads M , M and with the center or hub portion of the work-piece which, as aforesaid, is firmly held laterally or axially in said automatically clamped condition and revolvably supported by said piercers or centers E^6 , E^6 , while the work-piece is rotating, into the position shown in Fig. 2 in which position the work-piece or wheel is dished as shown. In this position, if necessary or desired, the rolls may still be in operation for giving the peripheral or flanged tread portion of the wheel or other article a harder wearing surface and also for finishing and truing up the work-piece or wheel or other article to the form or shape shown at F^2 in Fig. 2; or, instead of so reducing the constant pressure in said cylinder N , said dishing can also be done, while the work-piece is rotating, by increasing the constant pressure in cylinder O so as to overcome the constant pressure in cylinder N . During the dishing or rolling and dishing operation, the rim of the work-piece or wheel or other article is laterally supported and retained by the rolls, as shown in Figs. 1 or 2. After the wheel or other article is completely rolled, dished and finished, the rolls and the piercers or centers or supporting means are pulled back, as shown in Fig. 3, thereby placing the finished wheel F^2 or other finished article onto a positioning or raising, lowering and retaining device (see my said original application), which carries said finished wheel F^2 or other finished article to a position away from said piercers or centers or supporting means, and from there said finished wheel F^2 or other finished article is taken away by any suitable means and another properly heated ingot, bloom, blank or other work-piece put in place of it and centrally positioned and centered, or pierced or penetrated and centered, &c., as above described. In the positions shown in the Fig. 3, the piston-rods O^2 , O^3 and N^2 , N^3 and said piercers or centers E^6 , E^6 are pulled back and the finished wheel F^2 cleared to be removed as above described.

Said dishing, undishing or redishing operation while the work-piece is rotating may also be effected by retaining said work-supporting axles or work-supporting means in fixed positions while the work-piece is so rotatably supported at its center or hub portion by said supporting means and is so laterally clamped between said work-supporting means, by moving the rolls, for instance, J^1 , J^2 and K in a lateral direction. The marginal or rim portion of the work-

piece is thus moved laterally with respect to its center portion, or, for producing the same effect, both said work-supporting means and said rolls may be moved in opposite directions parallel to the axis of the supported work-piece while the latter at its center or hub portion is so supported and is so laterally clamped and while said rolls for instance J^1 , J^2 are so kept in contact 10 with the marginal or rim portion of the work-piece.

Undishing and redishing may be done in a similar manner as the dishing. In undishing, the object is placed on said piercers or supporting means and while so supported can be moved axially to suit the rolls and then undished while the object revolves.

In a dished wheel, the web, that is the part 20 of a wheel between the hub part and the rim part, is in an inclined position, as for instance in a wheel center F^1 in Fig. 10 or in the wheel F^2 shown in the Figs. 5, 6, 9, 25, 26 and 40, and in an undished wheel the web is 25 in a straight position, that is, at right angles with the axis of the wheel, or approximately so, as for instance in the undished finished wheel F^2 shown in the Fig. 7, and on this account, the said web is longer in the said 30 dished position than in the said undished or straight position; and, the extra length or difference between the length of the web of a dished and undished wheel has to be made up during the dishing process. In 35 case that a wheel has been finished by any means to the form or shape shown for instance at F^2 in Fig. 7, and, such wheel is to be dished to the form or shape shown for instance at F^2 in Fig. 5, in the usual 40 manner or through pressure in dies, then in such dishing process, the said web would have to be lengthened by direct extension of the metal in the web in the direction from the hub to the rim-part, or vice versa, which 45 would require an immense force and during such dishing process it will also be possible to twist the finished rim-part with its tread and flange and cause the wheel to be untrue and out of gage. Moreover, such methods 50 will leave an initial or inherent stress or strain in the finished wheel, which forces the wheel out of true when in service or when it is reheated, for instance, from the brake-shoes being pressed against the wheel, 55 or otherwise. All such difficulties are prevented with the method of dishing or rolling and dishing herein described, and the force or power required to do the dishing with such method will be very little, as can be 60 easily observed from the following:—With reference to the Figs. 4 and 5 for instance, Fig. 4 illustrates an ingot, bloom, blank or other work-piece rolled with the rolls J^1 , J^2 and K to the undished form or shape F^1 65 shown, the roll K having for instance the

peripheral or rolling face K^2 . Then with the rolls J^1 , J^2 still in operation, the herein named finishing rolls G^1 , G^2 and H , the roll H having for instance the peripheral or rolling face H^1 , commence operating against 70 the wheel, and the dishing may be commenced at the same time and in the manner before described, and when completely rolled and dished, the rolls J^1 , J^2 and G^1 , G^2 and H may still operate against the wheel to 75 its finish and to give to its tread and flange portion a harder wearing surface and roll the wheel perfectly true and to balance, also to gage or gages, as for instance illustrated in Fig. 5. The said necessary lengthening 80 of the web during dishing is performed during the dishing process by rolling out with the herein named web finishing rolls, for instance, G^1 , G^2 or G^0 , G^0 or G^4 as shown in the Figs. 5, 6, 7, 9 and 40, the metal f , f near 85 the inner rim-part as indicated by the clearance between the inner rim-part of the wheel and the web reducing roll parts j^{21} , j^{22} of the said rolls J^1 , J^2 or J^1 , J^0 or j^{21} , j^{22} or j^{23} of roll J^4 , which metal was left there by 90 said web reducing roll parts j^{21} , j^{22} of the herein named edging and web rolling rolls J^1 , J^2 or J^0 , J^0 or J^{21} , J^{22} or J^4 , as shown, and thereby adding, during the rolling and dishing process, sufficient metal to the web 95 part and providing thereby the required metal for the extra length to the web part, without producing such above described direct tension in the web and without leaving any stresses or strains in any 100 part of the so finished wheel.

Said work-supporting heads M , M provided with the axles E , E and their piercers or centers or supporting means, for instance E^1 , E^2 are located one at each side of the 105 work-piece as for instance shown in Figs. 1, 2 and 3, and said piercers or centers or supporting means with their axles will revolve with the ingot, bloom, blank or other work-piece in bearings of said work-supporting heads M , M and, during the piercing or centering, dishing or undishing, rolling and dishing or undishing processes, said supporting heads M , M with their axles E , E , and said piercers or centers or supporting means, for instance, E^1 , E^2 or E^3 , E^4 , etc., are moved longitudinally in line with the axis of the work-piece; that is, in line with the axes of said piercers or centers or supporting means, by means of the pressures 110 in the cylinders O and N (see Fig. 1) or by any other equivalent means, and are so moved toward or away from each other and may also be moved together in either direction; or, one of them may be retained in 115 any position while the other is moved toward or away from the one so retained during the piercing or centering process and are also longitudinally moved when removing said piercers or centers or supporting means 120.

from the work-piece or finished object. During the rolling and dishing or during the undishing, dishing, undishing and redishing processes said enters or supporting means are moved with the center or hub part of the work-piece, as the case may require and as and in the manner fully described in my aforesaid original application.

In rolling for instance car wheels or similar articles, the lateral thickness or width of the face roll K is the same as is the lateral thickness or width which the outer or rim portion of the car wheel is to have when finished, as shown for instance in the Figs. 4 to 9 inclusive and Figs. 23 to 25 inclusive and Figs. 38 to 40 inclusive; thereby, with said roll K and with the rolls for instance J¹, J² or J⁰, J⁰ or J², J⁴ or J⁶, J⁶ in said Figs. 4 to 9 and 23 to 25 inclusive and Figs. 37 to 40 inclusive, formed as shown and, with the peripheral rolling or operating face of said face roll K formed as shown as and for the purpose hereinafter described, for instance with reference to Figs. 4, 8, 18, 19, 20, 23 and 34, and with the inner rolling or operating portion of the web reducing roll part j²⁸ of each of the edging and web rolling rolls J¹, J², &c., formed sufficiently conical, as and for the purpose hereinafter fully described for instance with reference to Figs. 4, 8, 15, 16, 33 and 34, and, with all said three rolls situated in a plane passing laterally through the car wheel at one side of its axis and with said rolls moved and operated during the rolling process, as and for the purpose herein described, the metal in the peripheral face and total rim portion of the work-piece or car wheel is worked continually during the rolling process upon all its surfaces simultaneously, which to my knowledge, together with the result obtained thereby, was never done or accomplished before in rolling car wheels. In this manner the metal is uniformly condensed or refined to its maximum or practically so; that is to say, the metal in the whole rim portion except the metal forming the peripheral or flanged tread portion may be uniformly condensed or refined and to a greater extent than the metal in the central portion or hub and web portion, as shown at 3, Figs. 35 and 36, and the metal forming the peripheral or flanged tread portion may be condensed or refined to a greater degree than said metal in said rim portion as shown at 1 and 2 Figs. 35 and 36, thus giving more strength and a harder wearing surface to the metal forming said peripheral or flanged tread portion than has heretofore been obtained in rolling car wheels. By thus forming a car wheel or other similar article, it is also rolled smooth on all its surfaces and to the desired form or shape without leaving a raised circular portion or fin, which would have to be removed afterward by turning or other costly means.

Said web finishing rolls, for instance, G¹, G² or G⁰, G⁰ or G³, G⁴, &c., are both positively driven side rolls and are oppositely located, one at each side of the work-piece, as for instance shown in Figs. 1, 2, 3, 4 to 8, 10, 17 and 23, &c., and their shafts G, G are inclined to the sides of the work-piece. These web finishing rolls, during the rolling process, may operate against the web and inner rim part of the work-piece or wheel or other article, either together or independently of each other, and they are moved either together or independently toward or against or away from the work-piece or wheel or other article, as the case may require, by the pistons of pressure cylinders or pressure mechanism, or by any other equivalent means. If desired, said web finishing rolls may also be formed so as to form in conjunction with the tread or face finishing roll H at each side thereof, a stop for the lateral movements against the work-piece or wheel or other article, and thereby also assist in turning or driving the tread or face finishing roll H by frictional contact therewith; or said lateral movements of said web finishing rolls may be otherwise limited.

In most cases, said web finishing rolls are preferably formed for instance, as G¹, G² in Figs. 4, 5, 6, &c., that is, the part g¹³⁸ of each of said rolls G¹, G² is the herein named web finishing roll part, operating as shown on the web and inner rim part of the wheel or other article; and, the part g¹³⁷ of each of said rolls G¹, G² in the process illustrated in said figures is not operating against the work-piece, but in most cases is permitted to come in contact or to press against the opposite sides of the tread or face finishing roll H as shown, thereby forming the aforesaid stop for said web finishing rolls at or near the work-piece in the direction toward or against the work-piece and also assisting in turning or driving said tread or face finishing roll H by frictional contact therewith. Such rolls may be formed as for instance G³, G⁴ in Figs. 8 and 9, wherein the roll G³ is moved toward the workpiece from the position shown in Fig. 8 to the position shown in Fig. 9 in which position said roll G³ is retained during its operation against the work-piece until the wheel is dished and finished, and the said roll G⁴ with its said finishing roll part g¹³⁶, in finishing and dishing this wheel, which has its rim and hub parts extended on one side of said wheel only, as shown, is operating and is moved against the inner web and rim parts of said wheel, as shown in Fig. 9; or, such rolls may be wholly formed conical, as described in my said original application.

Said web finishing rolls, for instance G¹ and G², are connected together by equalizing mechanism as before mentioned and as fully described in my said original applica-

- tion. Said mechanism, when connected, equalizes the movements and pressures of said web finishing rolls toward or against the work-piece; that is, for instance, with 5 said rolls connected together, said rolls, for instance G^1 , G^2 are moved toward or against or away from the work-piece at both sides thereof, each the same distance as illustrated for instance in Figs. 17, 21 and 23 to 25.
- 10 For the rolling process illustrated for instance in Figs. 8 and 9, it is required that each one of the rolls, as for instance G^3 and G^4 shown in said Figs. 8 and 9, be moved laterally toward or against, or away from the 15 work-piece independently of each other, and in such case, said rolls G^3 and G^4 are disconnected from said equalizing mechanism without disconnecting said rolls from the co-operating pressure cylinders operatively 20 connected with said rolls. Said rolls will thereby be permitted to be moved laterally by the pressure cylinders operatively connected therewith toward or against, or away from the work-piece independently of each 25 other and, either one or both rolls may be retained in any desired position, as for instance shown in Figs. 8 and 9.
- Said edging and web rolling rolls for instance J^0 , J^0 or J^1 , J^2 , or J^3 , J^4 &c., are 30 positively driven side rolls and are oppositely located, one at each side of the work-piece, as for instance shown in Figs. 1, 2, 3, 4 to 8 and 10, 17 and 23, &c. When in normal position, their shafts J , J may either be parallel 35 or inclined to the sides of the work-piece, and during the rolling process they may operate alternately against the hub and adjacent web part, the web part, and the inner rim and adjacent web part, and also upon 40 the edges of the rim of the work-piece or wheel or other article either together or independently of each other; and, with their lateral moving device, may be moved laterally toward or against the work-piece or 45 away from it, or with the same, either together or independently of each other, by pistons of pressure cylinders or by any other suitable means, and with their shifting or longitudinally moving device may be moved 50 longitudinally in either direction, between the center or hub part and the rim part or periphery of the work-piece or wheel, or other article, forward and backward, such as the case may require, by pistons of pressure 55 cylinders or by any other suitable means. Said edging and web rolling rolls are formed so that during the rolling process they come in contact, or are against the opposite sides of the tread or face rolling roll 60 and thereby also form with the tread or face rolling roll K a stop for their lateral movement against the work-piece, and thereby also assist in turning or driving said face roll K by frictional contact therewith, or, 65 said lateral movements of said edging and web rolling rolls may be limited by any other suitable means.
- In most cases, the edging and web rolling rolls are preferably formed, for instance, as J^1 and J^2 in Figs. 4, 5, 6, 10, 13, 14, 15, 17, 21 and 23 to 25 inclusive, or for instance as J^3 , J^4 in Figs. 37 to 40 inclusive; the part j^{28} of such rolls J^1 , J^2 is the web reducing roll part, which may however have any other desired suitable form or shape than 75 herein shown, operating as shown alternately on the hub and adjacent web part, web part, and rim and adjacent web part of the work-piece, wheel or other article, that is, said web reducing roll parts j^{28} , j^{28} of said 80 rolls J^1 , J^2 , with their outer rolling or operating portions, are operating on the web and hub parts of the work-piece and form or shape the hub part as hereinafter described, for instance with reference to Figs. 11, 13, 14 85 or 21 and 23, or Fig. 38, and, with their inner rolling or operating portions are operating on the web part and the inner peripheral face or faces of the rim of the work-piece and roll said faces or inner rim portion sufficiently inclined toward the periphery of the work-piece, as and for the purpose herein-after fully described, for instance with reference to the Figs. 4, 8, 15, 16 and 33. The part j^{29} of each of said rolls J^1 , J^2 is the 90 edging roll part, rolling or operating as shown upon the edges or opposite sides of the marginal or rim part of the work-piece, wheel or other article, and also limiting the lateral flow of the metal therein between the 100 roll parts j^{28} , j^{28} of said rolls J^1 , J^2 and the periphery of the work-piece. Said roll parts j^{29} , j^{29} , during the rolling process come in contact with or are against the opposite sides of the tread or face rolling roll K , as 105 shown; or such rolls may not have such web reducing part j^{28} , but be for instance wholly formed conical as, for instance J^3 in Figs. 8 and 9.
- The rolling with said edging and web 110 rolling rolls may, in most cases, be commenced at or near the center portion of the ingot, bloom, blank or other work-piece, as for instance illustrated by the dotted lines for said edging and web rolling rolls in the 115 Figs. 4, 11, 17 and 21. In Fig. 11 for instance, the rolling may commence near the center portion of the blank or work-piece supported on said piercers or centers E^0 , E^1 , that is, at a suitable distance from the hub 120 which is to be formed onto said work-piece, as for instance indicated by the positions of the edging and web rolling rolls J^1 , J^2 shown in solid lines and, from these positions said rolls J^1 , J^2 are moved and forced laterally 125 into the opposite sides of said supported work-piece as shown by the dotted lines of said rolls J^1 , J^2 and from there said rolls J^1 , J^2 are shifted or moved longitudinally toward said center portion to form said hub 130

until said rolls are in contact with the peripheral faces of the flanges or shoulders e^{30} , e^{30} of said piercers or centers E^6 , E^6 , as indicated by the dotted end lines of said rolls. During this hub forming process, said shoulders e^{30} , e^{30} are also limiting the lateral flow of metal in said hub portion, which metal during said process has been forced laterally outward against said shoulders e^{30} , e^{30} and radially against said rolls J^1 , J^2 and has thus formed the hub portion shown by the dotted lines with an annular extension at each end of less diameter than any other portion of the hub. From their positions adjacent said shoulders e^{30} , e^{30} , said rolls J^1 , J^2 are shifted or moved longitudinally away from the hub, over their said starting positions, and toward the rim portion until said rolls have reached the positions shown for instance in the Figs. 1, 4 and 24. During this process, said rolls J^1 , J^2 may also be moved longitudinally forward and backward as often as desired; and, the rim portion of said work-piece be rolled with the rolls J^1 , J^2 and K to the form for instance shown in Fig. 4. The peripheral face of the work-piece will then have been rolled to a beaked or rudimentary form, as and for the purpose hereinafter described, for instance with reference to the Figs. 4, 8, 18, 19, 20 and 33, and the inner peripheral face or faces of the rim portion of the work-piece will have been rolled sufficiently inclined toward the peripheral face of the work-piece, as and for the purpose herein-after described, for instance with reference to the Figs. 4, 8, 15, 16 and 33. During the said process, said rolls J^1 , J^2 will in most cases be permitted to come in contact with or against the sides of the face roll K , as for instance shown or indicated by the dotted lines in Figs. 11, 17 and 21, or by the solid lines in Figs. 4, 5, 6, 10, and 23 to 25, or the lateral movement of said rolls may be limited by any other suitable means. Said edging and web rolling rolls may be shifted or longitudinally moved independently of each other; for instance in such a manner that, any one of said rolls may be retained in any position between their shifting limits and the other of said rolls, while operating on the work-piece, may be shifted forward and backward, such as the case may require, as for instance illustrated in Figs. 8 and 9. In Fig. 8, the edging and web rolling roll J^3 which in this case is formed wholly conical, is retained in the position shown, and therein, the work-piece during the rolling process is pressed against said roll J^3 with practically the same pressure with which the other roll J^4 may be pressed or held laterally against the work-piece. Under this pressure, the roll J^3 is operating against the whole side from the center or hub part to

the periphery of the work-piece, as shown; and the other roll J^4 during the rolling process, is also shifted or moved longitudinally by its power or pressure means operatively connected therewith (see my said original application), and with its said web reducing part j^{28} operates as before described on the web, hub and inner rim parts, and with its said edging roll part j^{29} operates as before described upon the edge or side of the work-piece F^1 . When the roll J^4 has reached the position, for instance shown in Fig. 8, then said roll J^3 is shifted or longitudinally moved and also laterally moved somewhat toward the work-piece, until said roll J^3 has reached the position shown in said Fig. 9, when the dishing and finishing of the finished wheel F^2 shown in Fig. 9 will commence and be done in the manner before described.

From the above it will be seen that, with the herein named edging and web rolling rolls formed as herein shown and, with the inner rolling or operating portions of the web reducing roll parts j^{28} , j^{29} of said edging and web rolling rolls J^1 , J^2 , &c., formed sufficiently conical, as and for the purpose herein fully described with reference to the Figs. 4, 8, 15, 16 and 33, an efficient rolling action is obtained, which during the formation of the web part toward the rim part, causes the metal to flow in the proper directions; that is to say, toward the rim part, within the latter and peripheral thereto. The lateral flow of the metal is limited by the roll parts j^{28} , j^{29} of said edging and web rolling rolls, and when this lateral flow of metal is thus arrested, the continued flow thereof will be peripheral to the rim. It will be observed that the radial flow of the metal is limited by the rolling surface of the tread or face rolling roll K , and when the radial flow is thus arrested, the continued flow of the metal will be peripheral to the rim, as for instance illustrated in Figs. 4, 15, 16 and 33. From this and from the matter described below with reference to the Figs. 4, 15, 16, 33, 34, 35 and 36, and with reference to other figures herein shown, it is to be observed that the metal, when being rolled from the blank or other work-piece into a car wheel or other article, is especially in the tread and flange or rim portion, not expanded radially, and therefore does not produce incipient cracks in the tread and flange portions of the rim, but is truly rolled and increases in density with increased working, thus giving to the metal both its due maximum strength and maximum resistance to wear. In other words, this method of rolling produces the same effect in the metal of the rim portion as if the web portion of the wheel were not in existence and the rim portion rolled its tota

width on its inner peripheral surface or surfaces as is done on its outer peripheral surface consisting of the tread and flange.

In Fig. 15 are shown such edging and web rolling rolls, for instance J^1 , J^2 , rolling or forming the web and rim parts of the partly shown work-piece F^1 central with the hub part, as shown and therein with the inner rolling or operating portions of the web reducing roll parts j^{28} , j^{28} of the edging and web rolling rolls J^1 , J^2 formed sufficiently conical as for instance shown and as and for the purpose hereinafter more fully described, the centers of the pressures caused by the so conically formed inner rolling or operating portions of said web reducing roll parts j^{28} , j^{28} of said rolls J^1 , J^2 are illustrated as acting at the center of the lengths of said conically formed inner rolling or operating portions and at right angles thereto against the work-piece, as is indicated by the arrows p and p^1 of said pressures, and the resultant pressure r from said pressures p and p^1 is therein indicated in the direction shown by the arrow for said resultant pressure r , and the actual flow of the metal will be in a lateral, radial and peripheral direction; that is, toward the rolls J^1 , J^2 and peripheral to the rim and in a radial and peripheral direction; that is, toward the periphery of the work-piece in the direction of the arrow r against the face rolling roll K (which roll K is not shown in this Fig. 15). From there the metal flows peripheral to the rim, and said lateral flow of metal is limited by the edging roll parts j^{29} , j^{29} of said rolls J^1 , J^2 from where the metal will flow peripheral to the rim, and said radial flow of metal is limited by the rolling surface of said tread or face rolling roll K (which roll K is not shown in said Fig. 15), from where the metal will flow peripheral to the rim. In Fig. 16 are shown such edging and web rolling rolls, for instance J^3 and J^4 , forming the web and rim parts of the partly shown work-piece F^1 which is to have its hub and rim parts formed at one side as shown and as before described with reference to Fig. 8. With the inner rolling or operating portion of the web reducing roll part j^{28} of the edging and web rolling roll J^4 formed sufficiently conical as for instance shown in Fig. 16 and as and for the purpose hereinafter more fully described, the total pressure p^2 , caused by the so sufficiently conically formed inner rolling or operating portion of said web reducing roll part j^{28} of said roll J^4 acting the total length of said conically formed inner rolling or operating portion and at right angles thereto against the work-piece, as indicated by the arrows p^2 for said total pressure, causes or forces the metal to flow against the face of said roll J^3 in the direction indicated by said arrows p^2 , and as the

metal in the work-piece cannot flow in said direction beyond the face of said roll J^3 , it will practically flow in a lateral, radial, and in a peripheral direction; that is, in a lateral direction against the roll part j^{29} of said roll J^4 and in radial direction in the direction of the arrow r^2 against the face rolling roll K (which roll K is not shown in this Fig. 16), from where it will flow peripheral to the rim; that is, toward and against the roll J^3 and toward and against the roll part j^{29} of the roll J^4 from where it will flow peripheral to the rim. Said radial flow of metal is limited by the rolling surface of the tread or face rolling roll K (which roll K is not shown in this Fig. 16), and from there the metal will flow peripheral to the rim.

Figs. 30 to 34 inclusive, which are sections of the rim portion of car wheels, illustrate diagrammatically the flow of metal caused by various forms of rolls, and therein the pressures caused by the rolls against the surfaces of the metal in contact with the rolls are assumed to be uniformly distributed at said surfaces, as indicated by the arrows pointing against said surfaces and the direction of the flow of metal from said arrows toward the inner region of the rim portion is indicated by the pressure lines of said arrows. The flow of metal illustrated by pressure lines parallel to each other indicates a uniform compression or uniform refinement of metal. The flow of metal illustrated by diverging pressure lines indicates that said uniformly distributed pressures at said surfaces in contact with the rolls are becoming less toward the inner region and peripheral face of the rim portion, and therefore the metal in those portions of the rim having said diverging lines is not condensed to the same degree as is the metal in the portions having parallel pressure lines and which degree of condensing becomes less and less as the distances between said diverging lines becomes greater; and if the rim is not rolled at its outer peripheral face simultaneously with the rolling of its inner peripheral faces, the metal will be extended instead of being compressed and thereby produce incipient cracks in the tread or outer peripheral face of the rim. The finished peripheral face of the car wheel is indicated by f^{12} and the outline of each of said sections is shown in heavy lines. In the Figs. 30, 31 and 32 the center line of the rim and adjacent web portion is indicated by y , and said inner face or faces of the rim portion in contact with the rolls are indicated by f^{16} . In Fig. 30, the portions of the rim in which the metal is not properly condensed are indicated by the distances d^1 , d^2 occupied by said diverging lines. In Fig. 31, the portions of the rim in which the metal is

not properly condensed is indicated by the distances d^3 , d^4 occupied by said diverging lines. The rolling of the rim portion as and in the manner described with reference to Figs. 30 and 31 does not properly work the metal in the rim and therefore forms a rim, which during the rolling process has already been weakened where its strength is needed and of which the tread will wear out quickly and shorten the life of such wheel, all of which may be observed on present wheels in actual use. In Fig. 32 is illustrated a section of a tire having for instance no web, such as used for some tired car wheels. From this figure it can easily be observed that the metal in such objects having a straight inner face without a web as shown, can be rolled to practically uniform density as indicated by the parallel pressure lines for the total pressure P ; and, the metal in the rim portion of car wheels and similar objects having each a web formed integral with the rim, can be rolled in accordance with my invention to practically uniform and maximum density, as can be done with rims having no web portion.

Therefore and in order to produce my improved car wheel or other like article, I form the inner rolling or operating portion 30 of the web reducing part j^8 of each of said edging and web rolling rolls for instance J^1 , J^2 , sufficiently conical, so that the face of said conically formed portion is sufficiently inclined from its lateral apex toward the inner end of its roll; that is to say, so that when for instance, the web reducing parts j^8 , j^{28} of said rolls J^1 , J^2 are against the finished web, the said face of said conically formed portion of each of said parts j^8 , j^{28} 40 is sufficiently inclined from the side of the web outwardly in the direction away from the axis of the work-piece, as for instance in Figs. 4, 8, 15, 16, 25 and 33. Said inclination of each of said web reducing parts j^8 , j^{28} I therefore form sufficiently large enough 45 so as to roll the inner peripheral faces of the rim portion sufficiently inclined outwardly toward the peripheral face of the work-piece so that during the rolling or forming of the rim portion for instance to the rudimentary form shown in Figs. 4, 8, 24 and 33 the metal is caused to flow in the proper directions to assure compression of the metal in said rim portion to uniform or 50 to practically uniform density, as is distinctly shown and diagrammatically illustrated in Fig. 33. In Figs. 33 and 34 is diagrammatically illustrated and distinctly shown the result of the rolling or forming 55 of the rim of a car wheel in accordance with my invention hereinbefore described with reference to Figs. 4 to 7 and to Figs. 15 and 16, &c. Fig. 33 distinctly shows what is meant by the herein used words "sufficiently conical" or "sufficiently inclined"

and therein is shown said rim portion rolled for instance to the rudimentary form shown in the Figs. 4 and 24, and also in dotted lines, said rim portion rolled to finished form, and the pressures p , p^1 are the same 70 described as with reference to Fig. 15; the pressure lines for each of said pressures p , p^1 being parallel to each other in the directions of the arrows and at right angles to said inclined faces of said roll parts j^8 , j^{28} . 75 The said pressures p , p^1 from said sufficiently inclined faces of said roll parts j^8 , j^{28} thus applied during the rolling or forming of said inner rim portion have rolled said inner faces f^8 , f^{28} of the so rudimentarily 80 formed rim portion sufficiently inclined, as distinctly shown by the pressure lines for each of said pressures p , p^1 , which has caused the metal during said rolling or forming of the rim portion to flow in the 85 proper directions to be compressed to uniform density, as distinctly illustrated by said parallel pressure lines for each of said pressures p , p^1 , while at the same time the pressures p^5 , p^6 against the lateral sides of 90 the rim from the edging roll parts j^2 , j^{29} of said rolls J^1 , J^2 have caused the metal to flow into the inner region of the rim in the direction of the arrows of the pressure lines for said pressures p^5 , p^6 and have rolled the 95 rim to desired lateral thickness. At the same time the pressure p^7 against the peripheral face of the rim portion from the face beaking or face roughing roll K having its rolling face K' formed as shown, has 100 caused the metal to flow also into the inner region of the rim in the directions of the arrows of the pressure lines for said pressure p^7 and has rolled said peripheral face to the beaked or rudimentary form K' , as 105 shown, thereby having rolled said metal in the rim and adjacent web portion simultaneously on all its surfaces by rolls situated in a plane passing laterally through said rim and adjacent web portion and therewith 110 having compressed said metal simultaneously on all its surfaces to uniform and maximum density, or practically so, while at the same time the rim portion has been rolled to said rudimentary form shown for 115 instance in the Figs. 4, 24 and 33. The so rudimentarily formed rim is then rolled, as hereinbefore described, with rolls situated at another point of the rim portion to finished form whereby its metal is still further condensed as and in the manner hereinbefore described for instance with reference to the Figs. 5, 7, 18, 19, 20, 35 and 36 and diagrammatically illustrated in the Fig. 34. In Fig. 34 said so rudimentarily formed 120 rim portion is shown in dotted lines, and the finished rim and adjacent web portion shown rolled during the finishing rolling process to finished form, is shown in heavy lines. During the finishing rolling process 125 130

with the rolls G^1 , G^2 and H operating against the rim portion at another point thereof, the web finishing rolls G^1 , G^2 with their web finishing roll parts g^{130} , g^{131} roll 5 said inclined faces f^{18} , f^{19} to the finished forms f^{20} , f^{21} , while the peripheral face finishing roll H rolls said beaked or rudimentarily formed peripheral face K' to the finished form f^{12} and while the edging roll 10 parts j^{20} , j^{21} of said rolls J^1 , J^2 (each of which rolls has now been moved somewhat toward the axis of the work-piece as hereinbefore described or as for instance indicated by the distance f^{24} in said Figs. 33 and 34) 15 are still operating in contact with the sides f^{22} , f^{23} of the rim at another point thereof and are limiting the lateral flow of metal and maintaining the lateral thickness in the rim to which the same has been rolled during 20 the rolling described with reference to Fig. 33; the combined action of said rolls J^1 , J^2 , G^1 , G^2 and H during said finishing rolling process roll or form the rim and adjacent web portion to the finished form 25 shown in Figs. 34, 35 and 36. The Figs. 33, 34, 35 and 36 distinctly show and diagrammatically illustrate that the metal in the whole rim portion except the metal forming the tread, flange and root of the flange is 30 rolled or worked to uniform or practically uniform density and to a greater extent of density than the metal in the central or hub and web portion as shown at 3 Figs. 35 and 36, and said metal forming the tread, flange 35 and root of the flange where the strength and resistance to wear is mostly needed is rolled or worked to still greater or to its maximum degree of density or refinement as shown at 1 and 2 Figs. 35 and 36. It is, of course, to be understood that in order to produce said results, the rim portion must be rolled first, for instance, to the rudimentary form as and in the manner described with reference to Fig. 33 before the same is 40 rolled to the finished form shown in the Fig. 34, and that the rolling of the said inclined faces f^{18} , f^{19} and the rolling of said beaked peripheral face K' to their finished forms during the finishing rolling process will not 45 disturb the density or refinement of the metal to which it has been compressed during the process described with reference to Fig. 33, but will compress the metal to still greater density or refinement, especially so 50 in the tread, flange and root of the flange where the strength and resistance to wear is mostly needed, as can easily be seen from said Figs. 34, 35 and 36.

From the foregoing it will now be observed that, in rolling for instance car wheels with the edging and web rolling rolls formed as herein shown and as and for the purpose described with reference to Figs. 4, 8, 15, 16 and diagrammatically illustrated in Figs. 65 33, 34, 35 and 36, and with the lateral thick-

ness or width of said tread or face rolling roll K being the same as the lateral thickness or width which the rim portion of the car wheel is to have when finished, as is for instance shown in the Figs. 4, 8, and 23 to 25 and diagrammatically illustrated in Fig. 33, thereby, and with said roll K formed as shown and as and for the purpose herein described with reference to Figs. 4, 8, 18, 19, 20 and diagrammatically illustrated in Figs. 33, 34, 35 and 36 and with the rolls J^1 , J^2 in said Figs. 4, 23 to 25 and in Fig. 33, formed as shown and as and for the purpose above described with reference to the Figs. 4, 15, 16, 33, 34, 35 and 36, or with the rolls J^1 , J^2 in said Fig. 8 formed as shown and as and for the purpose above described, and with all said three rolls for instance J^1 , J^2 and K situated in a plane passing laterally through the work-piece at one side of its axis, the metal in the peripheral face and the whole rim portion of the work-piece or car wheel is worked continually, during the rolling or forming of the rim to rudimentary form, upon all its surfaces simultaneously with said three rolls so formed and so situated as before said and as shown for instance in said Figs. 4, 8, 23 to 25 and Fig. 33, and in then rolling the so rudimentarily formed rim to finished form as and for the purpose 90 for instance described with reference to Figs. 15, 16, 33, 34, 35 and 36, which to my knowledge, together with the results obtained thereby as for instance above described with reference to the Figs. 4, 8, 15, 16, 18, 19, 20, 33, 34, 35 and 36, was never done or accomplished before in rolling car wheels, whereby the metal in said peripheral face and rim portion is mechanically refined or condensed with the greatest degree of refinement or 100 density in the metal of the tread, flange and root of the flange where the strength and resistance to wear is mostly needed, thereby giving the metal in said peripheral face and rim portion its required maximum and uniform strength and its due maximum and uniform resistance to wear; and, as any surplus of metal in the work-piece can be worked during the rolling process for instance into the inner rim and adjacent web 110 portion, the said peripheral face and the whole rim portion of the car wheel can also be rolled smooth on all its surfaces to the desired form without leaving a raised circular portion or fin, which would have to be removed afterward by turning or other costly means.

My improved car wheel or other article, may also be rolled, as for instance described in the following:—The properly heated 125 blank or work-piece F , for instance of the form shown in Fig. 17, having been pierced and centered as before described or which may be pierced either before or after the hub is formed or during the process of form-

ing or shaping the hub portion, is ready to be rolled and dished, for instance, into a car wheel having the form or shape shown at F^2 in Figs. 5, 26 or 35. The said web reducing roll H rolls said beaked or rudimentary rolling rolls J^1, J^2 may commence operating against both sides of the work-piece F , first forming the hub part in a similar manner as hereinbefore described with reference to Fig. 11 and also as shown by the dotted lines in Fig. 17. The shoulders or flanges e^{30}, e^{30} of said piercers or work-supporting centers E^1, E^2 limit the lateral flow of said metal in the hub part during the operation of forming the latter and with the end parts of said rolls J^1, J^2 limiting the radial flow of said metal and coming against the peripheral faces of said shoulders or flanges e^{30}, e^{30} , the ends of the hub part may be formed flat and to the desired gage for the length of the hub and the hub rolled or formed smooth on all its surfaces as hereinbefore described. When the hub part is so finished, the said edging and web rolling rolls J^1, J^2 are moved from the hub part toward the rim part, or are moved forward and backward as often as desired, and thus make the metal flow in the proper direction and roll or form the web part to its desired thickness and when said rolls J^1, J^2 are in the positions shown for instance in the Fig. 4 the inner face or faces of the rim portion have been rolled or formed to said rudimentary form, as and for the purpose hereinbefore described with reference to the Figs. 15, 16, 33, 34, 35 and 36. During this operation any lateral flow of the metal is limited by said edging roll parts j^{29}, j^{29} , and also during this operation, the tread or face rolling roll K with its rolling surface K^2 having the shape as shown in said Fig. 4, or as K^7 in Fig. 24 is limiting the radial flow of metal and is operating against the peripheral face of the work-piece to break the same, as and for the purpose herein described for instance with reference to the Figs. 18, 19, 20, 33, 34, 35 and 36, and in conjunction with said rolls J^1, J^2 roll the peripheral face of said work-piece to the beaked shape shown at F^1 for instance in said Figs. 4, 24 or 33. With the said rolls J^1, J^2 still operating with their roll parts j^{29}, j^{29} in contact with the work-piece in the positions shown for instance in Figs. 4, 24 or 33, or with said rolls moved somewhat toward the axis of the work-piece as before described or as for instance indicated by the distances f^{24}, f^{24} in Figs. 33 and 34 and with the said roll K in the same position shown in Figs. 4, 24 or 33, or with the roll K pulled back somewhat, the herein named web finishing rolls G^1, G^2 and tread or face finishing roll H commence operation against the work-piece F^1 and the dishing process may be commenced at the same time as and in the manner before described and roll and dish the work-piece to the form or shape of the dished car wheel F^2 shown for instance in the Figs. 5 or 25. When so completely rolled and dished, the said rolls J^1, J^2 and G^1, G^2 and H may still continue to operate in contact with or against the wheel as desired, whereby the wheel is made perfectly true and to balance and to gage or gages and its tread and flange surfaces made harder and smoother and more durable and, any surplus of metal may be forced to flow toward the inner rim and adjacent web portions into the space f^{16} in Fig. 25, whereby the rim portion is rolled smooth on all its surfaces without leaving a raised circular portion or fin which would have to be removed afterward by turning or other costly means. All the rolls and piercers or work-supporting centers are then pulled back, whereby said work-supporting centers are entirely removed from the so finished car wheel as and by the means before described, and the wheel removed and replaced with a new properly heated blank or work-piece. The above described operation is then repeated, all as and by the means before described.

In rolling for instance the peripheral face of car wheels or similar articles first to a beaked or rudimentary shape simultaneously with the rolling or forming the rim portion thereof to the rudimentary form shown for instance in Figs. 4 and 33, as and for the purpose hereinbefore described with reference to the Figs. 4, 15, 16, 33, 34, 35 and 36, and then to the finished form; the tread or face rolling roll K with its peripheral face formed for instance as shown in Figs. 4, 8, 23 or 33, &c., or a similar face, serves to break the peripheral face of the car wheel before rolling the same to finished form; that is, to roll the peripheral face of the car wheel to beaked or rudimentary shape, for instance, to such form as shown at K^2, K^6 or $K^7, &c.$, in the Figs. 18, 19 or 20, &c., such preliminary action is herein termed "beaking." During such beaking and rolling or forming process the metal in the whole rim portion of the work-piece or wheel is worked continually and simultaneously upon all its surfaces which gives the metal forming the tread, flange, and the whole rim portion of the wheel the required uniform strength and density absolutely necessary for maximum and uniform resistance. After this beaking action is completed, the finishing roll or rolls are brought into action and roll out of said beaked or rudimentarily formed peripheral face the finished form of the tread and flange of the wheel and roll the same to its desired finished diameter as, for instance, shown by the dotted lines f^{12} for said finished peripheral face in Figs. 18, 19 and 20 and diagrammatically illustrated in the Figs. 33 and 34, whereby the metal in the tread and flange and root of the flange is still

further condensed, and any surplus of metal in the rim portion is forced into the inner rim and adjacent web portion into the spaces f^{15} , f^{15} in Fig. 25. The wheel thus 5 rolled or formed has its metal uniformly condensed or refined to its maximum where it is subjected to greatest strain and wear, and at the point heretofore considered the weakest, and is rolled smooth on all its 10 surfaces without leaving a raised circular portion or fin anywhere on the so finished wheel.

When rolling for instance the peripheral face of a car wheel or work-piece with the herein named tread or face rolling roll K, 15 having its rolling face for instance as shown at K^2 in Fig. 4 or K^7 in Figs. 8, 24 or 33, simultaneously with the rolling with said edging and web rolling rolls J^1 , J^2 , &c., as and in the manner hereinbefore described, 20 the work-piece is first rolled to the form or shape shown by F^1 , wherein the inner peripheral face or faces of its rim have been rolled to rudimentary form, as and for the purpose hereinbefore described with reference to the Figs. 15, 16, 33, 34, 35 and 36, 25 and its outer peripheral face rolled to beaked or rudimentary form, as and for the purpose hereinbefore described with reference to the Figs. 18, 19, 20, 33, 34, 35 and 36; and then 30 rolling said inner peripheral faces of the rim with adjacent web portion and said beaked peripheral face of the work-piece or wheel to finished forms with the herein named web finishing rolls for instance G^1 , 35 G^2 or G^6 , G^6 or G^3 , G^4 and tread or face finishing roll H, as for instance shown in the Figs. 5, 7, 9, 25 or 34, thereby the metal in the flange, tread and the rim, where the strength of the wheel is mostly needed, will 40 be worked to greater density or refinement than the metal in the central or hub and web portions with the greatest degree of density or refinement in the metal of the tread, flange and root of the flange, thereby 45 giving to these parts by so rolling them the greatest possible strength and most efficient wearing surface, which result heretofore has not been accomplished to my knowledge.

A car wheel or similar article may also 50 be rolled and dished or not dished as and in the manner fully shown and described in my aforesaid original application; that is to say, for instance, instead of rolling and dishing a car wheel or similar article with 55 the use of all the rolls as herein described, for instance with reference to Figs. 1, 2, 3, Figs. 4 to 10, Fig. 17 and Figs. 21 to 25, a car wheel or similar article may also be 60 rolled and dished or not dished with only the use of the herein named edging and web rolling rolls for instance J^1 , J^2 and tread or face rolling roll K; or for instance, with only the use of the herein named edging and web rolling rolls, for instance J^1 , J^2 , 65 tread or face rolling roll K and the herein

named tread or face finishing roll H; and, said rolling with only the use of said three or said four rolls may in some cases give satisfactory results and, in said rolling with only the use of said three or said four rolls 70 the inner circumferential face or faces of the rim portion may also be rolled or formed sufficiently inclined as and for the purpose hereinbefore described with reference for instance to Fig. 33, and the peripheral face of 75 the rim portion rolled to any suitable form desired or rolled direct to desired finished form. With any of such arrangements, that is to say, with only the use of said three rolls, or with only the use of said four rolls, 80 the hub and web or central portion of the car wheel or similar article may be formed of metal of a certain density or refinement and the rim portion of said car wheel or similar article of metal of greater density 85 or refinement than the metal in said central portion.

In Fig. 6 is shown, for instance, a previously finished or worn car wheel supported by said piercers or work-supporting centers or forming dies E^2 , E^2 as before described, and thereon, the said previously finished or worn wheel, of which the tread, flange, rim and web parts are indicated by the dotted lines, is shown rolled for instance 90 larger in diameter to the size and form or shape of the finished rerolled or reworked wheel indicated by F^2 . The center portion of each of said piercers or work-supporting centers or forming dies E^1 , E^2 is in this case 95 for instance being forced into the bore of the hub of said car wheel to make said bore larger, while at the same time the annular flange of each of said piercers or work-supporting centers or forming dies is put over 100 the outer peripheral portion or diameter of said hub, as shown in said Fig. 6. Such previously finished or worn wheel, if desired, may also be rerolled or reworked to a smaller diameter, or be rolled true to its 110 original diameter or to any larger diameter, such larger diameter of course being limited to the metal in such previously finished or worn wheel. In the Fig. 7, is shown for instance, an undished wheel F^2 rolled to the 115 form or shape F^2 in a similar manner as before described, but without the dishing, as shown.

In the Figs. 8 and 9, is shown for instance a wheel rolled with its web part wholly at 120 one side thereof; in Fig. 8 is shown the first rolling of the ingot, bloom, wheel blank or other work-piece to the form or shape, indicated by F^1 , and therein, the one edging and web rolling roll J^3 formed wholly conical as shown, is moved to the position shown and there retained, while the other roll J^1 , 125 as before described, is forming or is finishing the hub part and the web part and together with the tread or face rolling roll K 130

having for instance the rolling face K^1 is rolling the work-piece to the form or shape indicated by F^1 wherein the inner peripheral face of its rim has been rolled to rudimentary form, as and for the purpose hereinbefore described with reference to the Figs. 15, 16 and 33, and its outer peripheral face rolled to beaked or rudimentary form, as and for the purpose hereinbefore described 10 with reference to the Figs. 18, 19, 20, 33 and 34. The roll J^1 is then moved to the position shown in Fig. 9, and the web finishing roll G^1 formed as shown is moved toward the work-piece F^1 into position against the side of the tread or face finishing roll H^1 , as shown, and said roll G^1 is retained in this position during its operation against the work-piece while the other web finishing roll G^2 formed as shown is moved as before 20 described toward and against the work-piece F^1 and operates against the inner rim and adjacent web parts and at the same time with the tread or face finishing roll H^1 , and with the edging and web rolling rolls J^1 , J^2 25 in the position shown in Fig. 9, or the roll J^4 may be moved somewhat toward the axis of the work-piece, the wheel is rolled and is dished, as and in the manner before described, to the finished form or shape F^2 shown in said Fig. 9.

In Fig. 10, for instance, a wheel center F^1 , such as used for instance in tired car wheels, is shown rolled and dished to the form or shape shown in a similar manner as before 30 described. Therein is illustrated also the herein named tread or face rolling roll K having the rolling face K^1 as shown and, the herein named tread or face finishing roll H^1 having the rolling face H^2 as shown.

40 In the Figs. 13 and 14, I have for instance, illustrated in brief, piercing and rolling process or steps such as I prefer to employ for piercing or centering and for rolling or forming the center or hub portion of my improved car wheel or other circular body as hereinbefore described with reference to Figs. 4, 11, 12, 17 or 29 and also described in my aforesaid original application.

In Fig. 13 a work-piece F is shown having 50 a thickness which is the same or is somewhat greater than the length which the hub of the wheel or other body is to have when finished. The work-piece F has been brought into the position shown by the aforesaid positioning 55 or raising, lowering and retaining device described in my aforesaid original application and in which position the outer portion or periphery of the work-piece is coaxial, or approximately so, with said piercers or work-supporting centers E^1 , E^2 and is being pierced or centered with said piercers or work-supporting centers E^1 , E^2 and, operated upon with the rolls J^1 , J^2 which, while 60 rotating the work-piece, are forced or rolled 65 against and into the opposite sides of the

work-piece for rolling or forming the hub and, during this process of forming the hub, the ends of said rolls J^1 , J^2 are either in contact with the peripheral faces of the flanges e^{20} , e^{20} of said centers E^1 , E^2 , as for instance 70 shown in Figs. 18 and 14, or come against said flanges e^{20} , e^{20} during the hub forming process, as hereinbefore described with reference to Figs. 4, 11 or 17 and also described in my aforesaid original application. The 75 hub is thus finished to the form shown for instance in Fig. 14, including the piercing or centering of the work-piece and the hub formed smooth on all its surfaces and to desired form or shape without leaving a raised 80 circular portion or fin which would have to be removed afterward by turning or other costly means.

In Fig. 14, the work-piece F shown in Fig. 13, is shown pierced by said piercers or centers E^1 , E^2 and rolled with said rolls J^1 , J^2 to the form F^1 shown, while the work-piece is supported by both said piercers or work-supporting centers E^1 , E^2 , as shown. Said 85 piercing or centering may be done either before or during the process of rolling the hub portion; and said positioning or raising, lowering and retaining device is moved away from the work-piece, either after or during the piercing or centering process.

The web reducing roll parts j^{20} , j^{20} of said edging and web rolling rolls J^1 , J^2 , J^1 , J^2 ; or J^4 , J^4 or any other rolls substituted therefor are in some cases shaped at their outer end-rolling or operating portions with extensions as for instance j^{20} , j^{20} of said edging and web rolling rolls for instance J^{20} , J^{20} shown in Figs. 37 to 40 inclusive and therewith form the narrow annular extensions 7, 7 at opposite ends of the hub 5, see Figs. 135 and 36. Said annular extension or flange 7 may be provided at one or both ends of the hub and is of less diameter than any other portion of the hub. Flat facing ends are thus formed which may also be of considerably smaller superficial area than if such extensions or flanges were not provided; and when turning or facing the end or ends of the hub to required length or gage, less metal is removed and considerable time saved 115 thereby as well as tools. This, therefore, also assures a considerable saving in the time required to keep the facing tools in proper condition and gives the product an individuality by means of which it may be 120 distinguished from other articles of the same class. Said annular extension or extensions are preferably formed by rolling a rabbet at one or both ends of the hub at the outer periphery to form outwardly facing shoulders 125 as shown and as for instance hereinafter more fully described with reference to Figs. 37 to 40 inclusive.

In the Figs. 21 to 27 inclusive, I have for instance, illustrated in brief, rolling or form-

ing process or steps such as I prefer to employ for completely rolling or forming and dishing the dished car wheel as hereinbefore described and also described in my afore-
5 said original application and shown, for instance, at F² in Fig. 5, or a dished car wheel similar thereto including the piercing or centering of the properly heated work-piece. In Fig. 21, the properly heated blank or
10 work-piece F has a thickness which is the same or somewhat greater than the length which the hub of the car wheel is to have when finished and, in Fig. 22, the properly heated blank or work-piece F has a thickness
15 which is, for instance, the same or somewhat greater than the lateral thickness or width which the marginal or rim portion of the car wheel is to have when finished. Fig. 21 shows said work-piece F brought into position by said positioning or raising, lowering and retaining device described in my said original application so that the outer portion or periphery of the same is coaxial, or approximately coaxial, with the piercers or
20 work-supporting centers E^a, E^b. In this case the piercers or centers have their lengths to suit the location of the web portion of the wheel, as shown; that is, the web portion of the car wheel in this case will be formed in
25 the center of the length of the hub of the car wheel and said centers E^a, E^b will both have the same length. In this position of the work-piece, said piercers or centers E^a, E^b are moved against the opposite sides of the
30 work-piece and the piercing or centering and the rolling or forming of the work-piece, including the rolling or forming of its hub portion, to the form of the work-piece shown at F in dotted lines, will begin and be per-
35 formed in the following manner:—During the piercing or centering process one work-supporting center E^a is moved axially from its position shown in solid lines into the position thereof shown by the dotted lines, in
40 which latter position the axial movement of said one piercer or center E^a is automatically stopped and is rotatably retained in said position during the rolling or operating process illustrated in Fig. 21, and during said pierc-
45 ing or centering process this one piercer or center E^a is also forced axially into one side of the work-piece until its shoulder or flange e³⁰ is against said side, as shown thereof by the dotted lines, and during said piercing or centering process the other piercer or center E^b is also forced axially into the other side of the work-piece from its position shown in solid lines to the position thereof shown by the dotted lines wherein the shoul-
55 der or flange e³⁰ of said other piercer or center E^b is against said other side of the work-piece as shown by the dotted lines, and thus the work-piece is rotatably supported at its center or hub portion by both said piercers or centers E^a, E^b. While so supported the
60 work-piece may also be automatically and firmly clamped between said piercers or centers E^a, E^b as hereinbefore described and be so retained in said clamped condition during the entire rolling or operating and dishing processes, until the work-piece is rolled and dished to finished form and ready to be re-
65 moved. The oppositely-arranged rolls J¹ and J² shown at one side of the axis of the work-piece are both simultaneously moved
70 equal distances during the hub forming process and are so moved either from their positions shown in solid lines to the positions thereof shown by the dotted lines, or are moved during the hub forming process as
75 hereinbefore described with reference for instance to Figs. 4, 11 or 17 and also described in my aforesaid original application, while the face beaking or face roughing roll K may begin to act against the peripheral face of
80 the work-piece as shown, thereby rolling the work-piece for instance to the form shown thereof in the dotted lines. In these latter positions said rolls J¹, J² are in contact with the peripheral faces of the shoulders or
85 flanges e³⁰, e³⁰ of said piercers or centers E^a, E^b, and, the edging roll portions j²⁸, j²⁸ of said rolls J¹, J² are then in contact with or against the opposite sides of the face roll K, as shown, and are limiting the lateral flow
90 of metal in the work-piece between the roll parts j²⁸, j²⁸ of said rolls J¹, J² and the periphery of the work-piece during the further rolling or operating process against the work-piece, and thus the work-piece F is
95 100 rolled, including the piercing and the rolling or forming of its hub portion, from the form in Fig. 21 shown in solid lines to the form in said figure shown in dotted lines. It is to be understood that said piercing or centering of
105 the work-piece may be done either before or during the rolling process above described and illustrated with Fig. 21, and that said positioning or raising, lowering and retaining device, as before described, may be moved
110 away from the work-piece either after or during the piercing or centering process. Fig. 23 shows said work-piece F so pierced or centered and rotatably supported and so rolled to the form shown, with its hub completely formed and with both said rolls J¹, J² in contact with or against the peripheral faces of the shoulders or flanges e³⁰, e³⁰ of said piercers or centers E^a, E^b. With the rolls J¹, J² thus positioned, the web portion
115 120 of the work-piece may be reduced or rolled to its desired thickness in the following manner, forming part of said rolling or forming process or steps:—Said rolls J¹, J² may be moved during the rolling or forming process
125 longitudinally from their positions adjacent the hub portion, shown in Fig. 23, to the positions adjacent the rim portion shown in Fig. 24, and during said longitudinal movements of said rolls J¹, J², the web reducing
130

roll portions j^{28} , j^{29} of said rolls J^1 , J^2 are also rolling or reducing the thickness of the web portion of the work-piece to its desired thickness and rolling the inner peripheral faces of the rim of the work-piece to the rudimentary form shown, as and for the purpose hereinbefore described with reference to the Figs. 15, 16, 33 and 34 and, while simultaneously with said longitudinal movements of said rolls J^1 , J^2 said face roll K is operating against the peripheral face of the work-piece and rolls the same to the beaked or rudimentary form, as for instance shown in Fig. 24 and as and for the purpose hereinbefore described with reference to the Figs. 18, 19, 20, 33 and 34; or said rolls J^1 , J^2 , when rolling said web portion to its desired thickness, may be moved longitudinally forward and backward as often as desired while simultaneously therewith said face roll K is against or is operating against the peripheral face of the work-piece and rolls the same to the said beaked or rudimentary form as shown for instance in Fig. 24 or 33. While the roll parts j^{28} , j^{29} of said rolls J^1 , J^2 are still operating in contact with the lateral sides of the rim portion, said finishing rolls G^1 , G^2 and H shown at the other side of the axis of the work-piece begin operating against the so rudimentarily formed rim portion and roll with said rolls G^1 , G^2 the so rudimentarily rolled inner peripheral faces of the rim of the work-piece to the finished form and roll with said roll H the so beaked or rudimentarily formed peripheral face of the work-piece to the finished form shown at F^2 in Fig. 25. At the same time the edging roll parts j^{28} , j^{29} of said rolls J^1 , J^2 are maintaining the lateral thickness of the rim to which the same has been rolled during the process and simultaneously with the operations of said rolls G^1 , G^2 and H against the work-piece the dishing may be done and dish the work-piece or wheel while the same is rotating to the form F^2 shown in Fig. 25; which dishing may be done in the same manner as before described, for instance with reference to Figs. 1 to 3, or in a manner similar thereto, or in any manner producing the same result. By such rolling or forming process, as for instance above described with reference to Figs. 21 to 27, the car wheel is pierced and is rolled and dished to the form F^2 shown in Fig. 25 and, any unnecessary surplus of metal in the work-piece or wheel may be forced during the rolling or operating process to flow either into the inner rim and adjacent web portions; that is, into the spaces indicated by f^{15} , f^{16} in Fig. 25; or, said surplus of metal may be forced into any other portion or portions of the work-piece or wheel without leaving a raised circular portion or fin anywhere on the so finished rolled wheel. When so completely rolled and dished, said rolls J^1 , J^2 and G^1 , G^2 and H may still be operating against the so rolled and dished car wheel, whereby said dished car wheel is rolled perfectly true and smooth, to balance, and to gage or gages; and its tread and flange surface made harder and smoother and more durable.

In Fig. 22, said piercers or centers E^a , E^b , during said piercing or centering process are moved or forced the proper equal distances or depths into both sides of the blank or work-piece, as indicated by the dotted lines for the same and in these positions the shoulders or flanges e^{30} , e^{30} of said centers E^a , E^b are spaced from the sides of the blank or work-piece the proper distances, or somewhat more than the proper distances required to make up the length which the hub of the car wheel is to have when finished, as and in the manner described in my original application, or in any other manner which produces the same result. The rolling or forming of the hub of the car wheel may also be done in a similar manner, as for instance hereinbefore described with reference to Figs. 11, 17, or 13 and 14, and, when the wheel is so completely rolled and dished; then all the rolls may be pulled back into the positions shown for instance in Fig. 3 and, said positioning or raising, lowering and retaining device is then again operated or moved, until it is in contact with the so finished dished car wheel, after which said centers E^a , E^b are pulled back into the positions shown, for instance, in Fig. 3, thereby placing said finished dished wheel onto said positioning or raising, lowering and retaining device and there-with removing the same from the apparatus or mill, &c., as and in the manner described in my said original application.

By such piercing or centering and rolling or forming processes or steps, as for instance above described with reference to Figs. 21 to 27 inclusive, for completely rolling and dishing car wheels or other circular bodies including said piercing or centering of the work-piece with my said preferred apparatus or mill, or with any other mill producing the same result, the blank or work-piece F , shown in solid lines in either of the Figs. 21 or 22, is pierced or centered and completely rolled in the same apparatus or mill with one heat to the completely rolled and dished finished car wheel F^2 shown in the Figs. 26 and 27, of which figures, Fig. 27 shows in plan view the so finished rolled and dished car wheel F^2 and, Fig. 26 a diametral section thereof taken on dotted line 26--26 Fig. 27, looking in direction of the arrows. When the car wheel is so completely rolled the flat faces of the hub extensions or flanges 7, 7 are faced as hereinbefore stated and the hub may be bored to proper size as shown at 6, Figs. 35 and 36. 130

The rolling process or steps illustrated for instance in Figs. 37 to 40 inclusive is similar to the rolling process or steps hereinbefore described with reference to Figs. 4, 5, and 5 Figs. 21, 23, 24 and 25 with the exception that in the Figs. 37 and 38 I have illustrated in brief such rolling or forming process or steps as hereinbefore referred to and, wherein the entire opposite end faces of the 10 hub of the work-piece are rolled or formed or operated upon directly with said edging and web rolling rolls and, for said purpose, said edging and web rolling rolls are preferably formed as J^{69} , J^{69} , that is, the parts 15 j^{43} , j^{42} of said rolls J^{69} , J^{69} are the roll parts adapted to roll or operate as shown upon the opposite end faces of the hub of the work-piece during the rolling or forming of said hub and, the parts j^{28} , j^{28} of said rolls 20 J^{69} , J^{69} are said web reducing roll parts, which may however have any other desirable suitable forms or shapes than herein shown, operating as shown alternately against part of the opposite end faces of the hub and 25 against the peripheral faces of the hub and adjacent web part, the web part, and the rim and adjacent web part of the work-piece. The parts j^{28} , j^{28} of said rolls J^{69} , J^{69} are said edging roll parts operating upon 30 and maintaining the lateral thickness of the rim and limiting therein the lateral flow of metal between said web reducing roll parts j^{28} , j^{28} of said rolls J^{69} , J^{69} and the periphery of the work-piece. In the Figs. 37 and 35 38 I have for instance illustrated in brief, piercing or penetrating or centering process or steps and the manner of rolling or forming, in this case, the entire center or hub portion of the work-piece or car wheel 40 or other circular body, including the rolling or forming of the entire opposite end faces of the hub with rolls, such as I prefer to employ in carrying out my invention. In Fig. 37 the properly heated blank or work-piece F, shown in diametral section, may have a thickness which is either the same or greater than the length which the hub of the car wheel or other circular body is to have when rolled to finish, or may have for instance 45 a lateral thickness or width which is approximately the same or greater than the thickness or width which the rim portion is to have when rolled to finish, and which blank or work-piece F has been brought into 50 the position shown and in this position it is pierced or centered at its opposite sides with the piercers or centers E^1 , E^1 and supported therewith and, operated upon with said rolls J^{69} , J^{69} , which rolls, while rotating the work-piece, are forced or rolled against and into 55 the opposite sides of the work-piece and are rolling or forming the hub. During this process of forming the hub, the end faces of the roll parts j^{43} , j^{43} of said rolls J^{69} , J^{69} are either in contact with the peripheral faces of said piercers or centers E^1 , E^1 , as for instance shown in Figs. 37 and 38, or come against said peripheral faces of said E^1 , E^1 during the hub rolling or forming process; thus the hub will be rolled to the 60 finished form shown for instance in Fig. 38, including the piercing or penetrating or centering of the work-piece, and the hub rolled or formed smooth by rolling with said rolls J^{69} , J^{69} on all its surfaces and to 65 desired form or shape without leaving a raised undesirable circular portion or fin which would have to be removed afterward by turning or other costly means. In Fig. 70 38 the work-piece E shown in Fig. 37, is 75 shown pierced by said piercers or centers E^1 , E^1 and rolled with said rolls J^{69} , J^{69} and K to the form as shown, while the work-piece is supported by both said piercers or work-supporting centers E^1 , E^1 , as 80 shown. It is to be understood that said piercing or penetrating or centering may be done either before or during said process of rolling the hub portion. The further operating process illustrated in Figs. 39 and 40 85 is similar to the process for instance described with reference to Figs. 24 and 25; that is, Fig. 38 shows said work-piece F so pierced or centered and rotatably supported and so rolled to the form shown and, with 90 both said rolls J^{69} , J^{69} in contact with the peripheral faces of said piercers or centers E^1 , E^1 . From the points of the rolls J^{69} , J^{69} thus positioned, the web portion of the work-piece may be reduced or rolled to its desired 95 thickness in the following manner, forming part of said rolling or forming process or steps illustrated in Figs. 37 to 40 inclusive:—Said rolls J^{69} , J^{69} during the rolling or forming process of the web, may be moved 100 longitudinally or radially with respect to the work-piece from their position adjacent the hub portion shown in solid lines in Fig. 38 and shown in dotted lines in Fig. 39, to the positions thereof adjacent the rim portion shown in Fig. 39. During said longitudinal or radial movements of said rolls J^{69} , J^{69} the web reducing roll portions j^{28} , j^{28} of said rolls J^{69} , J^{69} are also rolling or 105 reducing the thickness of the web portion of the work-piece to its desired thickness and rolling the inner peripheral faces of the rim of the work-piece to the rudimentary form shown, and as and for the purpose hereinbefore described. Simultaneously with said 110 longitudinal or radial movements of said rolls J^{69} , J^{69} said roll K is operating against the peripheral face of the work-piece and rolls the same to the beaked or rudimentary form as for instance shown in Fig. 39 and 115 as and for the purpose hereinbefore described; or said rolls J^{69} , J^{69} when rolling or reducing said web portion to its desired thickness, may be moved longitudinally or 120 radially with respect to the work-piece for 125 130

- ward and backward as often as desired, while simultaneously with said longitudinal or radial movements of said rolls J^{69} , J^{69} , said face roll K is against or is operating 5 against the peripheral face of the work-piece and rolls the same to said beaked or rudimentary form, as for instance shown in Fig. 39. While the roll parts j^{29} , j^{29} of said rolls J^{69} , J^{69} are still operating in contact with 10 the lateral or opposite sides of the rim portion, said finishing rolls G¹, G² and H, shown for instance at the other side of the axis of the work-piece, begin operating against the so rudimentarily formed rim portion and 15 roll with said rolls G¹, G² the so rudimentarily rolled inner peripheral faces of the rim of the work-piece to finished form and roll with said roll H the so beaked or rudimentarily formed peripheral face of the 20 work-piece to the finished form shown in Fig. 40, while the edging roll parts j^{29} , j^{29} of said rolls J^{69} , J^{69} are maintaining the lateral thickness of the rim to which the same has been rolled during the process. 25 Simultaneously with the operation of said rolls G¹, G² and H against the work-piece, the dishing may be done to dish the work-piece or wheel while the same is rotating, to the form F² shown in Fig. 40, which dishing may be done in the same manner as hereinbefore described, for instance with 30 reference to Figs. 1 to 3, or in a manner similar thereto or in any manner producing the same result.
- 35 The advantages of my invention are many and will be appreciated by those skilled in the art. Some of said advantages are for instance—The production of a car wheel having the metal in the flange, tread and 40 whole rim portion rolled or worked to greater density or refinement than the metal in the central or hub and web portions with the greatest degree of density in the metal of the tread, flange and root of the flange. 45 where the strength of the wheel and its resistance to wear is mostly needed, thereby giving to said parts the greatest possible strength and most efficient wearing surface which results in a car wheel much stronger 50 and of longer actual life or service than has heretofore been produced. A car wheel or other circular object thus rolled or formed results also in an enormous saving in the cost of operations during manufacture and the 55 product is also cheapened and the output increased; or for instance, the production of a car wheel wherein metal has been rolled from the rim portion onto the undished web portion during the rolling and dishing of 60 the car wheel to make up the extra length required in the dished web and to produce a wheel which is free or substantially free from initial or inherent stresses or strains which would tend to distort the wheel if subjected to strain or to heat; or for instance, 65

the production of a car wheel having an annular extension rolled at one or both ends of the hub, and when turning or facing the ends of the hub to required length or gage, considerable time is saved thereby as well as 70 tools; this, therefore, also assures a considerable saving in time required to keep the facing tools in proper condition and gives the product an individuality by means of which it may be distinguished from other 75 articles of the same class; or for instance, the production of a rolled car wheel free or substantially free from initial or inherent stresses or strains; or for instance, the production of a rolled car wheel having the metal 80 therein rolled of varied density in circular regions; or for instance, the production of a car wheel rolled smooth on all its surfaces and free from raised portions or fins; or for instance, the production of a completely 85 rolled car wheel formed integral and rolled smooth on all its surfaces with one heat; or for instance, the production of a car wheel rolled and its hub punched or pierced, all performed with one heat; or for instance, 90 the production of a rolled wheel which has been rolled to rudimentary form and then to finished form; or for instance, the production of a rudimentarily formed car wheel having the peripheral portion and inner peripheral face or faces of its rim portion 95 rolled to rudimentary form, so that the metal in said rim portion has been condensed or compressed to uniform or to practically uniform density; or for instance, the production 100 of a car wheel having its hub, web and rim formed solely by rolling pressure and evidencing the rolling of the car wheel throughout.

Where in the specification the word "co-axial" or "coaxially" is used with reference to the centering, or piercing or penetrating and centering, and to the positioning of a work-piece, &c., it is intended to mean "co-axial", or "approximately coaxial," &c. 105

Where in the specification and claims the words "ingot, bloom or blank" are used, it is intended to mean the work-piece to be operated upon, and the word "work-piece" is used herein in a broad sense and is intended 115 to include an ingot, bloom, blank, car wheel or any other unfinished or completely finished circular, or approximately circular object adapted to be rolled, rerolled, reworked or reformed either to entirely change its 120 shape, or only partly change its shape or outline, or to change its dimensions in whole or part, as desired. In other words "work-piece" means any circular, or approximately circular object to be operated upon. 125

Where in the claims reference is made to a car wheel or similar article, or any portion of a car wheel, or to the metal in the car wheel or any portion thereof, or matter of like import, it is intended to refer to a 130

car wheel before it is put in service; it being, of course, understood that after a car wheel is applied to a car and supports the weight of the car body, it is subjected to strains.

5 Where in the specification and claims the words "sufficiently conical" or "sufficiently inclined" are used with reference to the said inner rolling or operating portions of the web reducing roll parts j^{28} , j^{28} of said edging and web rolling rolls for instance J^1 , J^2 , or with reference to the inner peripheral face or faces of the marginal or rim portion of a work-piece or wheel or other object, it is intended to mean, the inclination of said 10 inner rolling or operating portions of said web reducing roll parts j^{28} , j^{28} being or to be formed, &c., so as to cause the metal, during the rolling or forming of said rim portion, to flow in the proper directions to assure 15 compression of the metal in said rim portion to uniform or to approximately uniform density, as distinctly illustrated in Fig. 33 and as hereinbefore fully described with reference to said Fig. 33. 4 and 5 constitute the web and hub portions or the central portion of the wheel or other article which may 20 also be termed the body portion of the wheel or other article.

The foregoing description clearly sets forth 30 various piercing or penetrating or centering and rolling or forming processes or steps and operations I prefer to employ in piercing or penetrating and centering and completely rolling and dishing, or working or 35 reworking properly heated ingots, blooms, blanks or other work-pieces into completely finished rolled car wheels or other circular articles embodying my invention, in the same apparatus with one heat. The method 40 of and apparatus or mill I prefer to employ for producing car wheels or other circular articles embodying my invention forms no part of this invention; this being claimed in other co-pending applications filed by me 45 and having the hereinbefore said serial numbers and filing dates.

The foregoing description and accompanying drawings further fully set forth my invention together with portions of an apparatus or mill for manufacturing the same, and also illustrate modifications in the arrangement and constructions of said portions of said apparatus or mill.

Certain features of my invention herein 55 described are not all claimed herein, but such features not herein claimed are covered by claims within applications filed by me and having the hereinbefore said serial numbers and filing dates.

60 It will be obvious to those skilled in the art that changes may be made without departing from my invention as defined in the claims.

I claim as my invention:-

65 1. A rolled car wheel or other rolled circu-

lar article having a hub and web or central portion and a rim portion formed integral with said central portion and whose central portion is formed or composed of metal having a given strength and whose rim portion 70 is formed or composed of metal of increased strength.

2. A rolled car wheel or other rolled circular article having a hub and web or body portion and a flanged rim formed integral 75 with the body portion and whose body portion is formed or composed of metal having a given strength and whose flanged rim is formed of metal of uniform or practically uniform density and of increased strength. 80

3. A rolled car wheel or other rolled circular article having a hub and web or central portion and a rim or marginal portion formed integral with said central portion and whose central portion is formed or composed of metal of a given strength, and whose rim or marginal portion except its tread and flange or peripheral portion is formed or composed of metal of increased 85 strength, and whose tread and flange or peripheral portion is formed or composed of metal of still greater strength. 90

4. A rolled car wheel or other rolled circular article having a hub and web or body portion and a tread and flange or peripheral portion formed integral with 95 said body portion and whose body portion is composed of metal of given refinement and whose tread and flange or peripheral portion is formed of metal worked to a 100 greater degree of refinement during the rolling of the wheel or other article.

5. A car wheel or other circular article having a hub and web or central portion and a rim or marginal portion formed integral with said central portion and whose central portion is formed or composed of metal of given refinement, and whose rim or marginal portion except its tread and flange or peripheral portion is formed or composed 105 of metal of super-refinement, and whose tread and flange or peripheral portion is formed or composed of metal of still greater refinement. 110

6. A rolled car wheel or other rolled circular article having a hub and web or central portion and a rim portion formed integral with said central portion and whose central portion is formed or composed of metal of given density and whose rim portion is formed or composed of metal of increased density. 115

7. A rolled car wheel or other rolled circular article having a hub and web or body portion and a tread and flange or peripheral portion formed integral with said body portion and whose body portion is formed or composed of metal of given density and whose tread and flange or peripheral portion is formed or composed of metal worked to in- 125 130

creased density during the rolling of the wheel or other article.

8. A car wheel or other circular article having a hub and web or central portion and a rim or marginal portion formed integral with said central portion and whose central portion is formed or composed of metal of given density and whose rim or marginal portion except its tread and flange or peripheral portion is composed of metal of increased density, and whose tread and flange or peripheral portion is formed of metal of still greater density.

9. A rolled car wheel or other rolled circular article having a hub and web or central portion and a rim portion formed integral with said central portion and wherein the carbon content is the same in the central portion as in the rim portion, but wherein 20 the metal comprising said rim portion is stronger than the metal in said central portion.

10. A rolled car wheel or other rolled circular article having a hub and web or body portion and a tread and flange or peripheral portion formed integral with said body portion and wherein the carbon content is the same in the body portion as in the tread and flange or peripheral portion, but wherein 30 in the metal forming the tread and flange or peripheral portion is rolled or formed harder and stronger uniformly or substantially so during the process of rolling or forming the wheel or other article, than the 35 metal in the body portion.

11. A car wheel or other circular article having a hub and web or central portion and a rim or marginal portion formed integral with said central portion and wherein the 40 carbon content is the same in the central portion as in the rim or marginal portion, but wherein the metal comprising the rim or marginal portion except the metal forming the tread and flange or peripheral portion 45 is stronger than the metal in the central portion, and wherein the metal forming the tread and flange or peripheral portion is harder and stronger than the metal in the portion of the rim or marginal portion 50 rounded thereby.

12. A car wheel or other circular article having a hub and web or central portion and a rim portion formed integral with said central portion, said central portion being 55 formed or composed of mechanically refined metal and the metal in the rim portion being super-mechanically refined.

13. A car wheel or other circular article having a hub and web or body portion and a flanged tread or peripheral portion formed integral with said body portion, said body portion being formed or composed of mechanically refined metal and the metal in the flanged tread or peripheral portion being

super-mechanically refined during the forming of the wheel or other article.

14. A car wheel or other circular article having a hub and web or central portion and a rim or marginal portion formed integral with said central portion, said central portion being formed or composed of mechanically refined metal, the metal in the rim or marginal portion except the metal forming the flanged tread or peripheral portion being super-mechanically refined, and the metal forming the flanged tread or peripheral portion being mechanically refined to a still greater degree.

15. As an article of manufacture, a car wheel or other rolled circular article formed integral and having a rolled or partly rolled hub portion, a rolled rim portion and a dished web portion connecting said hub and rim portions, the metal in said dished web being rolled free or substantially free from 85 stresses or strains.

16. As an article of manufacture, a dished car wheel or other circular dished article formed integral and having a rolled central portion or rolled hub and web portion, and 90 a rolled rim or marginal portion, the metal in said car wheel or other circular article being free or substantially free from stresses or strains.

17. As an article of manufacture, a rolled 95 dished car wheel formed integral and having its hub or a part thereof rolled and whose web forms the dished portion thereof and wherein the metal in said web is rolled free or substantially free from initial or inherent stresses or strains which would tend to force the wheel out of true if subjected to strain or to heat.

18. As an article of manufacture, a rolled 105 dished car wheel formed integral and having its hub or a part thereof rolled and wherein the metal is rolled free or substantially free from initial or inherent stresses or strains which would tend to distort the wheel if subjected to strain or to heat.

19. As an article of manufacture, a rolled 110 car wheel or other rolled circular article having a rim portion and a dished body portion formed integral with said rim portion, the metal in said dished body portion having a given strength and being rolled free or substantially free from initial or inherent 115 stresses or strains and said rim portion being formed or composed of metal of increased strength.

20. As an article of manufacture, a rolled 120 car wheel or other rolled circular article having a rim portion and a dished body portion formed integral with said rim portion, the metal in said wheel or other article being free or substantially free from stresses or strains, the metal in said dished body portion having a given strength and the metal

in said rim portion being of increased strength.

21. As an article of manufacture, a rolled car wheel or other rolled circular article having a rim or marginal portion and a dished body portion formed integral with said rim or marginal portion, the metal in said dished body portion having a given strength and being free or substantially free from stresses or strains, said rim or marginal portion except its tread and flange or peripheral portion being formed or composed of metal of increased strength, and said tread and flange or peripheral portion being formed or composed of metal of still greater strength.

22. As an article of manufacture, a rolled car wheel or other rolled circular article having a dished web portion, the metal of which is free or substantially free from initial or inherent stresses or strains which would tend to force the wheel or other article out of true if subjected to strain or to heat, the rim portion of said wheel or other article having the metal thereof rolled or worked to greater density than the remainder of said wheel or other article.

23. As an article of manufacture, a rolled car wheel or other rolled circular article formed integral and having a dished central or web portion, the metal in said car wheel or other article being substantially free from initial or inherent stresses or strains which would tend to distort the wheel or other article if subjected to strain or to heat, the rim portion of said wheel or other article having the metal thereof rolled or worked to greater density than the remainder of said wheel or other article.

24. As an article of manufacture, a rolled dished car wheel or other rolled circular dished article formed integral, the metal in said wheel or other article being free or substantially free from initial or inherent stresses or strains which would tend to distort the wheel or other article if subjected to strain or to heat, the metal in the central portion of said wheel or other article having a given strength, the rim or marginal portion of said wheel or other article except its tread and flange or peripheral portion being formed or composed of metal of increased strength, and said tread and flange or peripheral portion being formed or composed of metal of still greater strength.

25. As an article of manufacture, a rolled car wheel having a dished body portion including a rolled or partly rolled hub and a rim portion, the metal thereof being of varied density in circular regions with the tread or peripheral portion of greatest density and the metal of said dished body portion free or substantially free from initial or inherent stresses or strains.

26. As an article of manufacture, a rolled car wheel formed integral and having a dished body portion including a rolled hub and a rim portion, the metal thereof being free or substantially free from initial or inherent stresses or strains and being of varied density in circular regions with the metal in the tread or peripheral portion of greatest density.

27. As an article of manufacture, a rolled car wheel or similar article formed integral and having a dished body portion and a rim portion and being rolled on its exterior surfaces including its hub or a part thereof, the metal therein being substantially free from initial or inherent stresses or strains and being of varied density in circular regions with the metal in the rim or marginal portion of greatest density.

28. As an article of manufacture, a rolled car wheel formed integral and having a dished body portion and a rim portion, the metal therein being substantially free from initial or inherent stresses or strains and being of varied density in circular regions with the metal in the rim or marginal portion except the flanged tread or peripheral portion of greater density than the metal in said dished body portion, and with the metal in said peripheral or flanged tread portion of still greater density.

29. As an article of manufacture, a car wheel or other circular object having a dished body portion and a rim or marginal portion formed integral with said body portion, the metal in said body portion being mechanically refined and being free or substantially free from initial or inherent stresses or strains and the metal in said marginal or rim portion being super-mechanically refined with the greatest degree of refinement at the flanged tread or peripheral portion.

30. As an article of manufacture, a car wheel or other circular object having a dished body portion and a rim or marginal portion formed integral with said body portion and being free or substantially free from initial or inherent stresses or strains, the metal in said body portion being mechanically refined, and the metal in said rim or marginal portion being super-mechanically refined with the greatest degree of refinement at the flanged tread or peripheral portion.

31. As an article of manufacture, a car wheel or other circular article formed integral and having a dished web portion rolled free or substantially free from initial or inherent stresses or strains, a rolled hub portion and a rolled rim portion.

32. As an article of manufacture, a car wheel or other circular article formed integral and being rolled free or substantially

- free from initial or inherent stresses or strains, and having a dished portion, a rolled hub portion and a rolled rim portion.
33. As an article of manufacture, a car wheel or other circular article having a dished web portion rolled free or substantially free from initial or inherent stresses or strains, a rolled hub portion and a rolled rim portion, the metal in said rim portion being rolled to greater density than the metal in said web and hub portion.
34. As an article of manufacture, a dished car wheel or other dished circular article formed integral and being rolled free or substantially free from initial or inherent stresses or strains and having a rolled central or hub and web portion and a rolled rim or marginal portion, the metal in said rim or marginal portion being rolled to greater density than the metal in said central or hub and web portion.
35. As an article of manufacture, a dished car wheel or other dished circular article formed integral and being rolled free or substantially free from initial or inherent stresses or strains and having a rolled central or hub and web portion and a rolled rim or marginal portion, the metal in said rolled central or hub and web portion being rolled to a certain strength and the metal in said rim or marginal portion being rolled to greater strength than the metal in said central or hub and web portion.
36. As an article of manufacture, a dished car wheel or other dished circular article formed integral and being rolled free or substantially free from initial or inherent stresses or strains and having a rolled central or hub and web portion and a rolled rim or marginal portion, the metal in said rim or marginal portion except its tread and flange or peripheral portion being rolled to greater density or strength than the metal in said central or hub and web portion and the metal forming said tread and flange or marginal portion being rolled to still greater density or strength than the metal in the portion of the rim or marginal portion surrounded thereby.
37. As an article of manufacture, an integral car wheel rolled on its exterior surface including its hub or a part thereof and rolled uniformly free or substantially so from initial or inherent stresses or strains.
38. As an article of manufacture, an integral car wheel having a dished central portion and a rim and having been rolled free or substantially free from initial or inherent stresses or strains by rolling metal from said rim onto said central portion.
39. As an article of manufacture, a rolled integral car wheel having a dished central portion and a rim, said dished central portion having been rolled free or substantially free from initial or inherent stresses or strains by rolling metal from said rim onto said central portion during the dishing operation.
40. A car wheel having a hub portion, web portion and a flanged rim portion, said portions being integral and the carbon content thereof being the same throughout, but the metal in the rim portion being stronger than the metal in the hub and web portions with the tread and flange of said rim portion rolled harder and stronger than the remainder of said rim portion.
41. A rolled car wheel or other rolled circular article formed integral and having a rim portion adapted for wearing action, every or practically every portion of the metal in said rim portion being rolled to greater density than the remainder of said car wheel or other article during the rolling of the same.
42. A car wheel or other circular article formed integral and having a rim or marginal portion adapted for wearing action, the metal in said rim or marginal portion being rolled to greater density than the metal in the remainder of said car wheel or other article with the flanged tread or peripheral portion of said rim or marginal portion rolled to greatest density.
43. A completely rolled car wheel or other completely rolled circular article formed integral and having a body portion and a rim portion, the metal therein being rolled of varied density in circular regions with the outermost region forming the tread or peripheral portion rolled to greatest density during the rolling of the wheel or other article.
44. A completely rolled car wheel or other completely rolled circular article formed integral and having a body portion and a rim portion, the metal therein being rolled of varied strength in circular regions with the metal in the outermost region forming the tread or peripheral portion rolled to greatest strength during the rolling of the wheel or other article.
45. A car wheel or other circular article formed integral and having a body portion and a rim or marginal portion, the metal therein being of varied density in circular regions with the outermost region forming the tread or peripheral portion of greatest density and the circular region adjacent said outermost region of less density than the latter but of greater density than the adjacent circular region surrounded thereby.
46. A car wheel or other circular article formed integral and having a body portion and a rim or marginal portion, the metal therein being of varied density or strength.

- in circular regions with the metal in the outermost region forming the tread or peripheral portion of greatest density or strength and the metal in the circular region 5 adjacent said outermost region of less density or strength than the latter but of greater density or strength than the metal in the adjacent circular region surrounded thereby.
- 10 47. A car wheel or other circular article completely rolled on its exterior surfaces including the hub or a part thereof and having the metal thereof rolled to different density in adjoining circular regions, the 15 metal being rolled to increased density toward the periphery of the wheel or other article during the rolling of the same.
48. A car wheel or other circular article having a widened rim portion and the metal 20 therein worked to different density in circular regions, the outermost region forming the tread or peripheral portion being of greatest density and the remainder of the rim portion being of less density than said 25 tread or peripheral portion but of greater density than the remaining inner region.
49. A completely rolled car wheel including a hub portion rolled from an ingot, bloom, blank or other work-piece and having 30 surfaces forming angles which are free from fins or other undesirable projecting portion or portions.
50. A car wheel having the hub, web and rim integral and being rolled smooth on all 35 its surfaces and free from fins or other undesirable projecting portion or portions at the angles formed by such surfaces.
51. A rolled car wheel having the hub, web and rim integral and rolled smooth on 40 all its surfaces and to true form.
52. A completely rolled car wheel including a hub portion formed integral and rolled smooth on all its surfaces with one heat and free from fins or other undesirable 45 projecting portions.
53. A car wheel rolled from an ingot, bloom, blank or other work-piece and having a punched or pierced hub, a web, and a rim wider than said web, the angles and 50 surfaces of said hub, web and rim being free from fins or other undesirable projecting parts.
54. A car wheel rolled from an ingot, bloom, blank or other work-piece and having 55 its hub punched or pierced, all performed with one heat.
55. A car wheel rolled and completed with one rolling operation or with one heat and having a hub, a web and a rim all 60 smoothly rolled with the angles and surfaces thereof all formed free from fins or other undesirable projecting parts.
56. A car wheel formed with one heat and having a punched or pierced hub, a web and a rim, all surfaces and angles of which are 65 smoothly rolled and free from surplus metal which would have to be removed afterward.
57. A car wheel rolled with one heat without surplus metal which would have to be removed afterward, said wheel having the 70 metal smoothly rolled on all its surfaces and at its angles.
58. A rudimentarily formed car wheel having a rim whose outer periphery is rolled to conical or approximately conical form so 75 as to permit of being rolled to finished form with a tread having a flange.
59. A rudimentarily formed car wheel having a rim whose outer periphery is rolled with a concaved or conical portion and opposite cylindrical portions, one of said cylindrical portions being of greater diameter 80 than the other.
60. A rudimentarily formed car wheel having a rim portion whose outer periphery 85 is provided with two cylindrical portions and a concaved or conical portion between said cylindrical portions, one of said cylindrical portions being of greater diameter than the other, the periphery so formed being adapted to be rolled to finished form 90 with the tread and a flange.
61. A rudimentarily formed car wheel or other circular article having a rim portion and a web formed integral therewith, 95 the inner peripheral face or faces of said rim portion being rolled sufficiently conical or inclined outwardly toward the periphery of the wheel to have condensed or compressed the metal therein to uniform or to 100 practically uniform density, substantially as described.
62. A rudimentarily rolled car wheel formed integral and having a rim portion and a central or hub and web portion 105 formed integral with its said rim portion, the inner peripheral face or faces of said rim portion being rolled sufficiently conical or inclined outwardly toward the periphery of the wheel to have caused the metal to flow 110 in the proper direction and to have condensed or compressed the metal therein to uniform or to practically uniform density, substantially as described.
63. A rudimentarily formed car wheel 115 or similar article formed integral and having a central or hub portion, a web, and a marginal or rim portion, the outer periphery of said marginal or rim portion being rolled or formed with two cylindrical portions and a concaved or conical portion between said cylindrical portions, one of said cylindrical portions being of greater diameter than the other, and the inner peripheral face or faces 120 of said marginal or rim portion being rolled sufficiently conical or inclined outwardly to 125

- ward the periphery of the wheel or other article, substantially as described.
64. A rolled car wheel having its hub rolled at opposite ends with circular extensions of smaller diameter than the adjacent portion of the hub.
65. A rolled car wheel having opposite ends of its hub rolled with one extension at each end thereof.
- 10 66. A rolled car wheel rolled at each end of its hub with a rabbet to form a short end extension whereby the superficial areas of opposite end faces of the hub are diminished.
- 15 67. A rolled car wheel rolled with a circumferential shoulder near each end of its hub to diminish the size of the hub at opposite ends.
- 20 68. A car wheel rolled with a hub having short cylindrical end portions of smaller diameter than the remainder of the hub.
- 25 69. A rolled car wheel having a hub gradually diminished in diameter from a medial plane and having outwardly facing shoulders near each end and short annular reduced end portions whereby the ends to be faced present comparatively small surfaces.
- 30 70. A rolled car wheel having a rolled hub provided at one end with an outwardly facing shoulder and an end extension of smaller diameter than the medial portion of said hub.
- 35 71. A car wheel having a rolled hub provided with a bore and an outwardly-extending annular flange of smaller diameter than the remainder of the hub.
- 40 72. A rolled car wheel or similar rolled circular article having a hub and being completely rolled on all its exterior surfaces including its hub or a part thereof.
- 45 73. A rolled integral car wheel or similar rolled circular integral article having a hub and being completely rolled on all its exterior surfaces including its hub or a part thereof and formed with a preliminary central hole or a part or parts thereof.
- 50 74. A rolled car wheel or similar rolled circular article formed integral and having its hub rolled and being otherwise rolled smooth on all its surfaces.
- 55 75. A rolled car wheel or similar rolled circular article formed integral and having a rolled hub and formed with a preliminary central hole or a part or parts thereof.
- 60 76. A car wheel or similar article having a hub, a web and a rim formed solely by the action of rolls.
- 65 77. A car wheel or similar article formed integral and having a hub, a web and a rim formed solely by the action of rolls against all surfaces of the metal thereof.
78. A wheel having a hub formed by means of pressure rolls and evidencing the rolling thereof.
- 65 79. A car wheel or similar article having a hub, a web and a rim formed solely by rolling pressures, the entire hub, web and rim evidencing the rolling of the wheel throughout.
- 70 80. A car wheel or similar article formed integral and having a hub, a web and a rim formed solely by rolling pressures, the entire hub, web and rim evidencing the rolling of the car wheel throughout.
- 75 81. A wheel having a punched or pierced hub, a web, and a rim with a tread and flange, the exposed surfaces of which are formed to shape by rolling, the entire wheel evidencing the rolling of the wheel throughout.
- 80 82. A car wheel or similar article formed integral and having a punched or pierced hub, a web and a rim with a tread and flange, the exposed surfaces of which are formed or shaped by rolling, the entire car wheel or similar article evidencing the rolling of the car wheel or similar article throughout.
- 85 83. A wheel having a hub rolled with a circular extension at one or both ends of smaller diameter than the adjacent portion or portions of the hub and evidencing the rolling thereof.
- 90 84. A rolled car wheel or similar article formed integral and having a hub rolled with a circular extension at one or both ends of smaller diameter than the adjacent portion or portions of the hub and evidencing the rolling thereof.
- 95 85. A rolled car wheel or similar article having an integral rim, web and hub formed solely by rolling pressures and simultaneously dished.
- 100 86. A wheel having a hub, a web and a rim formed solely by the action of rolls applied to opposite sides thereof and to the periphery or peripheries of the rim and evidencing the rolling action.
- 105 87. A car wheel or similar article formed integral and having a central or hub and web portion and a rim portion and being formed or shaped solely by the action of rolls against the opposite sides and periphery or peripheries thereof and evidencing the rolling action.
- 110 88. A wheel rolled on all its exposed surfaces and having its hub rolled with evidence of distinction whereby the end faces of the hub are also reduced in superficial area.
- 115 89. A car wheel or similar article formed integral and being rolled on all its exposed surfaces and having its hub rolled with evi-

dence of distinction whereby one of or both the end faces of the hub are also reduced in superficial area.

90. As a product of manufacture, a car wheel or similar article having the exterior of its hub rolled with a shouldered end or ends giving evidence of individuality to the product.

91. As a product of manufacture, a car wheel or similar article formed integral and having the exterior of its hub rolled with a shouldered end or ends giving evidence of individuality to the product.

92. A car wheel or similar circular article having a rim, and a hub and web or central portion formed integral with its said rim and being completely rolled, rerolled, reworked or reformed including its hub or a part thereof solely by the action of rolls.

93. An integral car wheel or similar integral article having a hub, a web and a rim and being rolled or formed solely by the action of rolls and simultaneously dished, all performed with one heat.

94. An integral car wheel or similar integral article having a hub, a web and a rim and being rolled or formed solely by the action of rolls, all performed with one heat.

95. An integral car wheel or similar integral article having a hub, a web and a rim and being rolled or formed solely by the action of rolls and simultaneously dished and also being free from surplus of metal which would have to be removed afterward, all performed with one heat.

96. An integral car wheel or similar integral article having a hub, a web and a rim and being rolled or formed solely by the action of rolls and being free from surplus of metal which would have to be removed afterward, all performed with one heat.

97. An integral car wheel or similar circular article being rolled, rerolled, reworked or reformed solely by the action of rolls and simultaneously dished.

98. An integral car wheel or similar circular article being rolled, rerolled, reworked or reformed solely by the action of rolls and simultaneously undished.

99. An integral car wheel or similar article being rolled, rerolled, reworked or reformed solely by the action of rolls and simultaneously undished and again redished.

100. A circular integral object having a hub and being rolled or formed from a car wheel or similar circular body solely by the action of rolls.

101. An integral car wheel or similar circular article rolled or formed from a worn car wheel or similar circular body solely by the action of rolls, said car wheel or similar article being rolled to smaller diameter than

said worn car wheel or similar circular body.

102. A circular article having a rim, and a hub and web or central portion formed integral with its said rim and being completely rolled or formed from an object solely by the action of rolls.

103. A circular article having a rim and a central portion including a hub formed integral with its said rim and being completely rolled or formed from an object solely by the action of rolls.

104. A car wheel or similar circular body rolled or formed from an ingot, bloom, blank or other work-piece and having a rim, and a hub and web or central portion formed integral with its said rim, the outer peripheral face of its said rim being rolled or formed to any desired form or shape and the inner peripheral face or faces of said rim being rolled or formed sufficiently conical or inclined outwardly toward the outer periphery of said rim to have condensed or compressed the metal in said rim to uniform or to practically uniform density, substantially as described.

105. A car wheel or similar circular body rolled or formed from an ingot, bloom, blank or other work-piece and having a rim, and a hub and web or central portion formed integral with its said rim and being rolled or formed solely by the action of rolls and simultaneously dished, the outer peripheral face of its said rim being rolled or formed to any desired form or shape and the inner peripheral face or faces of said rim being rolled or formed sufficiently conical or inclined outwardly toward the outer periphery of said rim to have condensed or compressed the metal in said rim to uniform or to practically uniform density, substantially as described.

106. A car wheel or similar circular article rolled or formed from an ingot, bloom, blank or other work-piece and having a rim, and a hub and web or central portion formed integral with its said rim, the outer peripheral face of its said rim being rolled or formed to any desired form or shape and the inner peripheral face or faces of said rim having been first rolled or formed sufficiently conical or inclined outwardly toward the outer periphery of said rim to have condensed or compressed the metal in said rim to uniform or to practically uniform density, substantially as described, said inner peripheral face or faces so rolled or formed having been then rolled to desired finished form.

107. A car wheel or similar circular article rolled or formed from an ingot, bloom, blank or other work-piece and having a rim,

and a hub and web or central portion formed integral with its said rim and being rolled or formed solely by the action of rolls and simultaneously dished, the outer peripheral face of its said rim being rolled or formed to any desired form or shape and the inner peripheral face or faces of said rim having been first rolled or formed sufficiently conical or inclined outwardly toward the outer periphery of said rim to have condensed or compressed the metal in said rim to uniform or to practically uniform density, substantially as described, said inner peripheral face or faces so rolled or formed having been then rolled to desired finished form.

108. A car wheel or similar article having a rim, and a hub and web or central portion formed integral with its said rim, the outer peripheral face of said rim having been first rolled or formed with two cylindrical or approximately cylindrical portions and a concaved or conical portion between said cylindrical portions of which one of said cylindrical portions has been rolled to greater diameter than the other, said peripheral face so formed having been then rolled to desired form with a tread and flange or to a similar form, and the inner peripheral face or faces of said rim having been rolled sufficiently conical or inclined outwardly toward the outer peripheral face of the wheel or similar article to have condensed or compressed the metal in said rim to uniform or to practically uniform density, substantially as described.

109. A car wheel or similar article having a rim, and a hub and web or central portion formed integral with its said rim and being rolled or formed solely by the action of rolls and simultaneously dished, the outer peripheral face of said rim having been first rolled or formed with two cylindrical or approximately cylindrical portions and a concaved or conical portion between said cylindrical portions of which one of said cylindrical portions has been rolled to greater diameter than the other, said peripheral face so formed having been then rolled to desired form with a tread and flange or to a similar form, and the inner peripheral face or faces of said rim having been rolled sufficiently conical or inclined outwardly toward the outer peripheral face of the wheel or similar article to have condensed or compressed the metal in said rim to uniform or to practically uniform density substantially as described.

110. A car wheel or similar circular article having a rim, and a hub and web or central portion formed integral with its said rim, the outer peripheral face of said rim having been first rolled with two cylindrical or

approximately cylindrical portions and a concaved or conical portion between said cylindrical portions of which one of said cylindrical portions has been rolled to greater diameter than the other, said peripheral face so formed having been then rolled to desired form with a tread and flange or to a similar form, and the inner peripheral face or faces of said rim having been first rolled sufficiently conical or inclined outwardly toward the outer peripheral face of the wheel or similar article to have condensed or compressed the metal in said rim to uniform or to practically uniform density, substantially as described, said inner peripheral face or faces so rolled or formed having been then rolled to desired finished form.

111. A car wheel or similar circular article having a rim, and a hub and web or central portion formed integral with its said rim and being rolled or formed solely by the action of rolls and simultaneously dished, the outer peripheral face of said rim having been first rolled with two cylindrical or approximately cylindrical portions and a concaved or conical portion between said cylindrical portions of which one of said cylindrical portions has been rolled to greater diameter than the other, said peripheral face so formed having been then rolled to desired form with a tread and flange or to a similar form, and the inner peripheral face or faces of said rim having been first rolled sufficiently conical or inclined outwardly toward the outer peripheral face of the wheel or similar article to have condensed or compressed the metal in said rim to uniform or to practically uniform density, substantially as described.

112. A car wheel or similar article having a rim and being rolled or formed from an ingot, bloom, blank or other work-piece, the inner peripheral face or faces and the outer peripheral face of its said rim having been first rolled or formed to rudimentary forms or shapes and then to desired finished forms, substantially as described.

113. A car wheel or similar article having a rim and being rolled or formed from an ingot, bloom, blank, or other work-piece and having been rolled or formed solely by the action of rolls and simultaneously dished, the inner peripheral face or faces and the outer peripheral face of its said rim having been first rolled or formed to rudimentary forms or shapes and then to desired finished forms, substantially as described.

114. An integral car wheel or similar ar-

title rolled on its exterior surfaces, including its hub or a part thereof, and being completely rolled or formed solely by the action of rolls and, when bored and forced or put onto its axle or shaft, having a peripheral face or faces of the hub and the peripheral face of the rim of said wheel or similar article coaxial with said axle or shaft and being truly balanced, or practically so.

115. An integral car wheel or similar article rolled on its exterior surfaces, including its hub or a part thereof, and being

rolled or formed solely by the action of rolls and simultaneously dished and, when bored and forced or put onto its axle or shaft, having the peripheral face of said wheel or similar article coaxial with said axle or shaft and being truly balanced, or practically so.

In testimony whereof, I have hereunto set my hand.

LOUIS F. DIETER.
